TRAIN DISPATCHING SYSTEM FOR
RAILROADS

Neil D. Preston, Rochester, N. Y., assignor to
General Railway Signal Company, Rochester,
N. Y.

Application April 4, 1929, Serial No. 352,553

71 Claims. (Cl. 246—3)

This invention relates to dispatching or centralized control systems for enabling an operator or dispatcher to control the movement of switches and signals over an extended territory, subject to the protection of a suitable block signal system, so as to facilitate and expedite train movement, the invention being more particularly directed to a system of communication to and from the dispatcher's office for obtaining the necessary indications and controls.

In a dispatching system, it is essential that the dispatcher or operator be advised of the movement of trains in the territory under his supervision. This may be done by transmitting to the dispatcher's office an indication, commonly known as an OS indication, when a train passes a known distant point, that is, when a train enters and leaves a track section. Since the movement of trains may be such as to require a transmission of a number of such OS indications at the same time, it is desirable to embody a communication system of the so-called synchronous type as distinctive from a code type.

In the synchronous type communication system, to which the present invention relates, the controls and indications to and from the dispatcher's office are transmitted over channel circuits, automatically set up in rapid sequence over a signal or message line and a common wire between the dispatcher's office and several control points along the track, the indications or controls being transmitted sequentially by the energization or de-energization of these channel circuits from sources of current located at the dispatcher's office or at the distant control points. Such a synchronous type system, using rotary selectors or distributors, is shown and described, for example, in my prior Patent No. 2,082,462 granted June 1, 1937 on an application filed June 16, 1927.

In the synchronous type of communication system, since the channel circuits must be set up one at the time in sequence, with each channel circuit maintained for such time as is required to transmit the desired indication or control, the total time cycle for setting up all of the channel circuits for the dispatcher's territory is increased as the system is extended to include more channel circuits for a greater number of controls or indications. Since a given channel circuit is set up only once in this total time cycle, it will be evident that the greater the time of this cycle, the greater is the possible time delay in transmitting a control or indication; and in many instances in the handling of traffic, too great a delay in obtaining a response to a lever movement or in

receiving an OS indication seriously handicaps the dispatcher in obtaining efficient and expeditious movements of traffic. For these reasons, it is desirable to limit the setting up of the channel circuits of the synchronous type selecting system to those actually required to transmit a new control or indication.

Under ordinary conditions of handling railway traffic, the dispatcher is frequently able to determine in advance the location in his territory where train movements are likely to occur next which will require him to make a change in the position of switches or indications of signals; and it is desirable that the dispatcher should be able at will to confine the channel circuit selection to a particular place or part of the territory under his supervision, so as to obtain quick response to lever manipulation and prompt OS indications. In thus restricting the operation of the communication system to a selected portion of his territory, the dispatcher of course for the time being is out of communication with the rest of the territory; but under the circumstances existing when the dispatcher manually restricts the channel circuit selection to a selected portion of the territory, he will not be interested for the time being in OS indications from the rest of the territory, nor desire to control any switches or signals at other places.

With these and other conditions in mind, it is proposed in accordance with the present invention to provide a communication system of the synchronous type in which communication is established between the dispatcher's office and each of several stations or other divisions of the dispatcher's territory one at a time in turn by sectionalizing the system into stations or corresponding divisions, and transferring the communication to the dispatcher's office from section to section in turn. Another feature of the invention is that the channel circuits for these stations or sections are set up only as required to transmit a new indication or control. Also, in accordance with this invention, the system is organized so that the dispatcher, by a simple manual manipulation, may restrict the channel circuit selection to a given selected station at any time and for as long as he desires.

In accordance with this invention, the channel circuit selection at the several way-stations, and also preferably in the dispatcher's office, is obtained by groups or series of sequentially operated neutral relays, such neutral relays for channel circuit selection being advantageously employed with sectionalized communication or station se-

lection, because the number of such relays required at each station need be no more than necessary to set up the channel circuits for that particular station.

5 Other characteristic features, functions and advantages of the system of this invention will in part be apparent as the description progresses, and will in part be pointed out from time to time as the proposed structure and mode of operation 10 of the system are explained.

As illustrative of one specific embodiment of the invention, there is shown on the accompanying drawings a typical organization of devices and circuits, constituting the equipment for the 15 dispatcher's office and the way-stations, for the application of the system to a single track railroad; but it should be understood that the system may be employed for the control of switches, signals or other devices, and for the indication of 20 the operation of such devices or train movements, in various other ways. The parts and circuits are shown in the drawings diagrammatically, with certain conventional illustrations, more with the object of making it easy to understand the principles and mode of operation of the system, rather than for the purpose of showing the particular 25 constructions or arrangements preferably adapted in practice.

In the accompanying drawings, Fig. 1A and 30 Fig. 1B illustrate the equipment in the dispatcher's office; Fig. 2A shows the equipment at the station A nearest the dispatcher's office; Fig. 2B shows certain parts of another station B and the station Z farthest from the dispatcher's 35 office; Fig. 3 shows certain parts and circuits, partly in the dispatcher's office and partly at one of the stations, which are involved in automatically starting the system into operation; Fig. 4 shows the line circuits and relays involved in 40 establishing communication with one station at a time, these parts and circuits being shown in the condition which they assume when the system is sectionalized; Fig. 5 illustrates the parts and circuits, partly in the dispatcher's office and 45 partly at a station, which relate to the testing to determine if channel circuits have to be set up for that particular station to transmit a new OS indication or control; and Figs. 6 and 7 show modified forms of the line circuits and relays for 50 sectionalizing the system.

Fig. 1A above Fig. 1B is intended to show the arrangement and organization of the equipment for the dispatcher's office; and Figs. 2A and 2B, placed end to end, are intended to show how the 55 system is arranged to include the station equipment. A complete system involves duplication of many of the parts and circuits shown, depending upon the number of stations involved, as will readily be apparent as the description progresses.

60 *Equipment at the dispatcher's office.*—At the central control station, conveniently termed the dispatcher's office, where the operator or dispatcher is stationed, the equipment comprises in general a suitable track diagram or model board of the track layout of the territory under the supervision of the dispatcher, with small electric lamps or other indicators to register the OS indications; a series of manually operable levers, by means of 65 which the dispatcher is able to control the operation of the switches, signals, and other devices, at several stations; a plurality of channel selecting devices, one for each station, preferably in the form of a group or bank of neutral relays; a power operated rotary circuit controlling device, 70 conveniently termed a station selector, for estab-

lishing the necessary inter-connection between the groups of channel selecting relays, and other devices of the dispatcher's office equipment, and for transferring communication from the dispatcher's office to each station in turn; an impulse producing means, preferably in the form of relays, for providing the necessary impulses for causing the sequential operation of the groups of channel selecting relays as required; and various other relays and auxiliary circuits for providing automatic starting and stopping of the system, manual station selection, and other functions. 10

As representative of the track diagram, there is shown in Fig. 1A a single passing siding S, 15 with a lamp 6 located near each end to indicate, when lighted, that there is a train present on the usual short detector track circuit at the corresponding end of the corresponding siding in the field. In practice, this diagram of course 20 comprises a large number of stretches of track, either single or double, with passing siding, crossovers, and the like, according to the character of the railroad in the territory under the supervision of the dispatcher; and the lamps 6, together with the means for controlling them, are 25 duplicated to provide for the desired OS indications at the various points in the control territory. Similar lamps, when properly controlled over a corresponding channel circuit, may be 30 used to indicate the position of the distant switches or signals, or to communicate to the dispatcher any other desired information.

Each of the OS lamps 6, as shown in Fig. 1A, is controlled by an OS relay 7 of the polar type 35 having a dead-beat armature 8 retained in one or the other extreme position, depending upon the polarity of current last flowing through the winding of this relay. In order that the lamp 6, when first lighted and until recognized by the dispatcher by a manual manipulation, may be 40 readily distinguished from all the other lamps on the track diagram which may be lighted, provision is preferably made so that the lamp 6 is intermittently lighted or flashed, until the dispatcher pushes a button, whereupon the lamp shines steadily with reduced brilliancy, until automatically put out. For this purpose, a cam 9, 45 rotated by a small electric motor 10, or other suitable means, operates a spring contact finger 50 11 to intermittently connect one terminal of a source of current, marked (—), to a bus 12. When the OS relay 7 is energized with the correct polarity, assumed to be negative, its contact finger 8 assumes the dotted line position, 55 establishing a circuit from the other terminal of said source, marked (+), over wire 13, through lamp 6, wire 14, back contact 15, of the relay 16, and wire 17 to the bus 12, so that the lamp 6 is intermittently lighted as the cam 9 rotates 60 and energizes the bus 12. When the dispatcher pushes a button 18, and moves the armature 15 in position to be attracted and held by the relay 16, the lamp 6 is energized steadily in series with the relay 16, and with reduced brilliancy, due to 65 the additional resistance of the relay 16 in the circuit. When the OS relay 7 is operated to return its contact finger 8 to the normal position, the lamp 6 goes out and the relay 16 is de-energized, permitting its armature 15 to return 70 to the normal position.

As representative of the levers manually operable by the dispatcher, there is shown in Fig. 1A a lever L, arranged to be moved up and down to either of the two extreme positions, this lever 75

being intended to be used for the control of the power operated switch at the end of the siding just above this lever. Another lever LS, movable from an intermediate or middle position, as shown, to the right or left, to either of two extreme positions, is intended to be used for controlling the signals at the corresponding end of the distant siding, and selecting the direction in which traffic may be permitted to move at that end of the siding. The various levers in the dispatcher's office are identified with the corresponding portions of the track diagram by position, number, or the like.

The levers L and LS, and all other levers in the dispatcher's office, are each provided with contacts which are normally closed during the movement of such lever from its existing position to some other operated position. In the simple form diagrammatically shown, a switch arm 20 is suitably connected to the lever L so as to move therewith, and engages a contact 21 momentarily as this lever is moved from one extreme position to the other. Similarly, the other lever LS has connected thereto a switch arm 22, arranged to engage contacts 23 momentarily, whenever this lever is shifted from any existing position to another operated position.

The levers L and LS are arranged to make and break contacts for the control of their respective devices; and in the diagrammatic arrangement shown, the lever itself carries insulated contact pieces 24 for connecting contacts indicated as arrows. In the case of the lever LS, which has three operated positions, a cam 25, movable with the lever, is arranged to engage a roller on a spring contact finger 26 and shift it to one position, as shown, when said lever is in its middle position, so as to engage a contact, illustrated as an arrow, and to allow the finger 26 to move to the other position and engage another cooperating contact, also indicated as an arrow, when said lever is in either of its extreme positions.

Referring to Fig. 1B, the rotary circuit controller of the station selector SS, in the simplified form shown, comprises a shaft 30, indicated by dot-and-dash lines, which is arranged to be driven by suitable electric motor 31 through a friction clutch 32. It is contemplated that the motor 31 is constantly operating, tending to drive the shaft 30, and that the clutch 32 slips while the shaft 30 is held stationary and the system is at rest. This is merely a typical arrangement, and various other devices may be employed for driving the shaft 30.

The rotation of the shaft 30 is controlled step-by-step by a suitable escapement device, which as shown comprises an escapement wheel 33, having teeth spaced around its periphery, corresponding to the number of stations of the system. The space between two successive teeth represents a movement of the shaft 30 from one station position to the next, this constituting one full step of the escapement wheel 33. The escapement wheel 33 is advanced one-half step at a time by the operation of suitable detent devices 34 and 35, actuated by stepping magnets 36 and 37 from the spring held engaging position. Upon energization of the stepping magnet 37 and retraction of the detent 35, the shaft 33 may rotate clockwise, in the direction shown by the arrow, one-half step, where it is stopped and held by the other detent 34; and upon energization of the other stepping magnet 36 and retraction of the other detent 34, the escapement wheel 33

and shaft 30 advance another half step, making one full complete step.

Fixed to the shaft 30 are contact arms 40, 41, 42, 43, and 44, arranged to engage stationary contacts in different positions of the shaft. The 5 full step positions of these arms are shown in dotted lines. These arms are connected to suitable wires, these connections as shown being direct, but in practice being made through suitable slip rings. These arms are of course insulated from each other. Also fixed to the shaft 30 is a cam 45, which is arranged to operate a spring contact finger 46 to open and close a circuit in different positions of the shaft, as hereinafter explained.

In the dispatcher's office, for each station of the system, there is a group of relays and other devices, which are the same for each station, so that a description of one will serve for all. This group of devices for each station comprises 20 a bank of neutral relays for the selection of the channel circuits for the corresponding station. One bank of such relays 1, 2, 3, and 4, is shown in Fig. 1B, as representative of the channel circuit selecting relays for station A. There will be 25 as many of these channel circuit selecting relays as required for the number of channel circuits for the corresponding station. Associated with these channel selecting relays for each station is a lever relay LV, a test relay TS, and a manually operable circuit controller K.

The equipment in the dispatcher's office also includes a line relay LR, a channel circuit impulse relay CI, with two associated relays 48 and 49; a starting relay ST; and a transfer relay TR, with its associated slow pick-up relays 50 and 51.

The system employs four line wires, comprising a common wire C, a signal or message line SGL, a stepping line STL, and a transfer line 40 TRL, which extend from the dispatcher's office throughout the territory under the supervision of the dispatcher and are connected to each of the stations in the manner hereinafter explained.

As shown, the system is arranged to be operated by direct current; and for this purpose suitable batteries, motor generators, or other suitable sources of current are employed. One of these sources of current, represented by the battery 52 is used for energizing circuits wholly local to the dispatcher's office; and for simplicity, the terminals of this source are identified as (+) and (-), and the local circuits are shown as terminating at (+) and (-). The other source of current, represented by the batteries 53 and 54, is employed for transmitting direct current of opposite polarities over the line circuits to the various stations; and for this purpose the midpoint of these batteries is connected to the common C, and the other terminal of these batteries, 60 which are of opposite polarity, are identified as (B+) and (B-), the wires connected to these terminals being for simplicity marked (B+) or (B-).

Station equipment.—Fig. 2A shows the station equipment representative or typical of the station at one end of a passing siding PS. Although other track lay-outs, with various arrangements of switches and signals may of course be controlled by a similar station equipment, the equipment for station A, shown in Fig. 2A, is assumed to be adapted to control the operation of a suitable power operated switch machine and the clearing of signals 55, 56, 57, and 57a, subject to track circuit control, and also for transmitting to 75

the dispatcher's office an OS indication that the usual detector track circuit at the end of the siding, provided with a track relay T, is occupied by a train. The operation of the switch machine 5 (not shown) is intended to be controlled to the normal or reverse position by a dead-beat polar relay 58, with suitable provisions for approach and detector locking. The clearing of the signals 55, 56, 57 and 57^a, subject to track circuit control and the position of the switch, is determined by the position of the dead-beat armature of the polar relay 59, the clearing of the particular signals for opposite directions of traffic being determined by the position of the dead-beat armature 10 of the polar relay 60. These relays 58, 59 and 60 are controlled over channel circuits from the dispatcher's office, as hereinafter explained. The way in which these relays control the operation of the switch machine and signals may take various forms, such as shown, for example, in my prior application, Ser. No. 199,325, filed June 16, 1927, now Patent No. 2,082,462 granted June 1, 1937 or in the application of S. N. Wight, Ser. No. 321,185, filed November 22, 1928, now matured 25 into Patent No. 1,889,457 granted November 29, 1932.

The track relay T controls two neutral relays 62 and 63, which are arranged to store up the indication of the occupied or unoccupied condition 30 of the detector track circuit, until such indication has been transmitted to the dispatcher's office, in a manner more easily explained in connection with the description of the operation.

At each station is a bank of neutral channel 35 circuit selecting relays, corresponding in number to those in the dispatcher's office. The channel circuit selecting relays for station A in Fig. 2A are designated 1^a, 2^a, 3^a, and 4^a, and correspond with relays 1 to 4 inclusive shown in Fig. 1B. These two banks of relays, one in the dispatcher's office, and one at the corresponding station, are operated synchronously and sequentially by impulses on the stepping line STL, to establish in 40 rapid sequence the channel circuits required to transmit the desired control or OS indications for station A. These channel circuit selecting relays at each station (see Fig. 2A) are controlled by a line relay, as LR^a for station A, of the polar type, having its armature or contact fingers biased 45 to the middle or neutral position. The line relay LR in the dispatcher's office is of the same type.

Also located at each station is a polar transfer relay TR, having a dead-beat armature remaining in the position it was last put; a transfer 50 stick relay TRS, of the neutral type having two windings; and a double-wound slow release relay SL.

At each station is a suitable source of current 55 for energizing local circuits, and another source for imposing different polarities of currents between the signal line SGL and the common wire C. These sources of current are preferably storage batteries, maintained trickle charged in a suitable way, and are shown the same as for the 60 dispatcher's office as batteries 52, 53, and 54, with the same symbols for their terminals and connection to the common wire C.

Operation

70 The parts are shown in Figs. 1A, 1B, 2A, and 2B, in the normal or inactive position, with the system at rest, ready to be automatically started whenever it becomes necessary to transmit a control or indication.

75 In this normal condition shown, in the dis-

patcher's office (see Fig. 1B), the starting relay ST, the transfer relay TR and the associated relays 50 and 51, the channel impulse relay CI and associated relays 48 and 49, and the stepping magnets 36 and 37, are all de-energized. 5 The channel circuit selecting relays, as 1, 2, 3, and 4, the lever relays LV and the test relay TS, for each of the stations, are also de-energized. The line relay LR in the dispatcher's office is also de-energized.

10 At each of the stations (see Figs. 2A and 2B), the transfer relay TR is de-energized, but its contact fingers are held to the right, in the position to which they were last operated by a positive impulse. The transfer stick relay TRS is 15 also de-energized. The slow release relay SL is maintained energized by a stick circuit from (+) through its front contact 66, wire 67, its lower winding, wire 68, through back contact 69 of the relay TRS, to negative (-).

The transfer line TRL is completed through all the stations to the last station Z through the back contacts 71 of the several transfer stick relays TRS. The stepping line STL is also completed through all of the stations, up the last 25 station, through the back contacts 72 of the several transfer stick relays TRS. As the last station Z (see Fig. 2B) the transfer line TRL is connected to common C. The stepping line STL is open circuited at the last station.

30 The several transfer relays at the several stations are connected in multiple between the transfer line TRL and common C through the upper winding of the slow relay SL, this connection being traced (see Fig. 2A) as follows:—from the 35 transfer line TRL, wire 73, relay TR^a, wire 74 and 75, upper winding of relay SL, wire 76, back contact 70 of the relay TRS, to C.

Starting.—The system is arranged so that it is automatically set into operation either by the 40 movement of any lever in the dispatcher's office to a new operated position, or by the entering or leaving of a train at any one of the detector track circuits so as to cause a change in the position of the corresponding track relay T. In other 45 words, whenever a new control or OS indication is to be transmitted, the system is automatically set into operation.

Considering first how the system is automatically started upon a new lever movement, when 50 any lever in the dispatcher's office is manually moved to a new operated position, the contacts associated with that lever, such as 20—21 and 22—23 (Fig. 1A), are momentarily closed to energize the corresponding lever relay LV. If the 55 lever L, for example, is the one which is moved from the upper position shown to the lower position, the closing of the contacts 20—21 during this movement establishes a circuit from positive (+), through contacts 20—21, wires 78, 79, 60 and 80, relay LV to negative (-). The relay LV, when thus energized momentarily, is maintained energized by a stick circuit from negative (-), through LV, wires 80 and 81, front contact 82 of the relay LV, wire 83, back contact 84 65 of the relay 1, wire 85, back contact 86 of relay 2 to positive (+). This stick circuit is also established through the front contacts 84 and 86 of the relays 1 and 2 and the wire 87, for reasons hereinafter explained.

70 Whenever any relay LV is energized, the closing of its front contact 88 connects positive (+) over wire 89 to the starting bus 90, which is connected by wire 91 to the lower winding of the starting relay ST to negative (-). Thus, 75

when any lever is operated to a new position, the starting relay ST is energized, and is maintained energized by a stick circuit from negative through the lower winding of the relay ST, wires 91 and 92, front contact 93 of the relay ST, wire 94, and contact finger 46, operated by the cam 45, to (+).

The starting relay ST may also be energized to start the system into operation whenever any track relay changes to a different position. Referring to Fig. 2A, assume that the track relay T is de-energized, by the entrance of a train into a corresponding detector track circuit. The dropping of the track relay T energizes the relay 62, over a circuit readily traced on the drawings; and as the relay 62 attracts its armature, its make-before-break contacts 95 momentarily close and establish a pick-up circuit for the relay 63. The relay 62, when picked up, is stuck up through its front contact 96 and the front contact 97 of the relay 63. The relay 63, when picked up, is stuck up through a stick circuit from negative (-), relay 63, wire 98 and 99, front contact 100 of relay 63, wires 101 and 102, back contact 103 of the channel circuit selecting relay 3^a to (+). A stick circuit for the relay 63 may also be established over wire 104 and front contact 105 of the channel circuit selecting relay 4^a, for reasons hereinafter explained.

The energization of the relay 63 in this way closes its front contact 106 and establishes an energizing circuit for the upper winding of the starting relay, which may be traced as follows (see Fig. 2A):—starting at C, front contact 106, of relay 63, wire 107, front contact 108 of the relay SL, wire 109, contact 110 of the transfer relay TR^a in its right or positive impulse position, wire 111 and 112 to the signal line SGL, thence to the dispatcher's office through arm 41, wire 113, upper winding of the starting relay ST to (B+). There is a similar starting circuit for each station, which is closed if the relay 63 at that station is energized. The two windings of the starting relay ST are, of course, so arranged as to act cumulatively if both should happen to be energized at the same time.

A starting circuit is established the same way at any station, when the system is at rest, if the track relay T at that station should happen to pick up, due to movement of a train out of the corresponding detector track circuit. Assuming that the OS indication of occupancy of the detector track circuit has been transmitted, as hereinafter explained, so that the relay 63 has been de-energized, the relay 62 is maintained energized only by its pick-up circuit, while the track relay T de-energized; and the relay 62 is at once de-energized when the train leaves the detector track section and the track relay T picks up to open its back contact. Upon such de-energization of the relay 62, its make-before-break contacts 95 momentarily close to energize the relay 63, which is stuck up as already described, and establishes the starting circuit through its front contact 106, as just explained.

In this way, whenever there is any change in track circuit conditions, or any lever movement, the starting relay ST is energized and the system set into operation.

Sectionalizing.—The first step in the operation is to sectionalize the system, so to speak, so that communication is established between the dispatcher's office and the first station A. As above pointed out, in the normal condition of the system when at rest, both the transfer line TRL

and stepping line STL are completed through the several stations, and the first step in the operation is to break up or sectionalize the transfer line TRL and the stepping line STL, so that they go only as far as the first station A.

Upon energization of the starting relay ST, and the closing of its front contact 114, a circuit is established for energizing the stepping magnet 37 (see Fig. 1B) from (+) through arm 40, wire 115, front contact 114 of the relay ST, wires 116 and 117, stepping magnet 37 to (-). This releases the escapement wheel 33, and allows the shaft 30 to turn clockwise, in the direction indicated by the arrow, one-half step, where the switch arms 46—44 occupy the position midway between the initial position and the first dotted line position. In this half-step position, a negative impulse is applied to the transfer line TRL from (B-) over arm 44, wire 118, relay TR in the tower, and wire 119 to the transfer line TRL, and thence along this transfer line through the several transfer relays TR at the various stations in multiple. This negative impulse through the transfer relays TR causes the relays TR, TRS and SL to assume the positions shown in Fig. 4.

Referring to Fig. 4, the contact fingers of the transfer relays TR are all in the left hand or negative impulse position. In this position a local circuit is established from (+) through the contact finger 120 of the relay TR to the left, wire 121, upper winding of the transfer stick relay TRS to negative (-). This energizes the relay TRS which interrupts the stepping line circuit STL at its contact 12 and the transfer line circuit TRL at its contact 71. The opening of the back contact 69 of the relay TRS also breaks the stick circuit for the relay SL, which is de-energized, since its pick-up circuit is broken at the back contact 70 of the relay TRS. In this connection, it should be noted that the relays TRS are made sufficiently slow in picking up that each of the transfer relays TR will be energized long enough to shift their contact fingers before the transfer line TRL is broken up by the opening of the back contacts 71 of the relays TRS.

At the first station A, nearest to the dispatcher's office, the stepping line STL is connected to the line relay LR^a at that station through the front contact 72 of the relay TRS and wire 122 to common C, so that the line relay LR in the dispatcher's office, and the line relay LR^a at station A are connected in series over the stepping line STL and common. With this stepping circuit for station A completed, through the energization of the relay TRS at that station, the stepping line circuit is energized with a negative impulse to shift contact fingers of the two line relays to the left hand position, this negative impulse being applied to the stepping line STL (see Fig. 1B) from (B-) through back contact 123 of the relay 49, wire 124, relay LR, and wire 125 to the stepping line STL. The reason for this negative impulse will be explained later.

After this operation of sectionalizing has been completed, the slow pick-up relay 50, which has been energized (due to the movement of the contact finger 126 of the relay TR in the dispatcher's office to the left) closes its front contact 127 and applied positive (+) over wire 128 to the bus 129 connected by wire 130 to the stepping magnet 36. The energization of the stepping magnet 36 allows the escapement wheel 33

and shaft 30 to make another half-step, completing the first full step in the operation.

In this first full step position of the shaft 30, the stepping magnet 37 is again energized through arm 40 and contact 131, wire 132, and over wire 115 through the front contact 114 of the starting relay, etc., as hereinbefore pointed out. This energization of the stepping magnet 37 advances the shaft 30 another one half-step, bringing the parts into the position shown in Fig. 5, which corresponds to the position for testing or determining whether or not channel circuits shall be set up for the first station A. In this position, the cam 45 has disengaged the finger 46, breaking the stick circuit for the starting relay ST; but the relay ST does not release its armature unless all of the relays LV are then de-energized, which occurs at some subsequent point in the operation of the cycle of the system when all of the channel circuits have been cleared out, as hereinafter explained.

Test for channel circuit selection.—For reasons to be explained presently, it is desirable to determine automatically, upon selecting each station, whether or not there is any new control or indication to be transmitted for that station, and then go through the operation of setting up the channel circuits only if such new control or indication is to be transmitted. For this purpose, a circuit, conveniently termed a test circuit, is established between the dispatcher's office and each station in turn as it is selected, and through the medium of this circuit, together with the condition of the corresponding lever relay LV, it is automatically determined whether or not the individual channel circuits for that station shall be set up.

To explain this feature of the operation, assume that, since the system last operated and cleared out all of the channel circuits, either a lever for station A was operated to a new position, or that the track relay T at station A had picked up or dropped. In either of these cases, there would be a new control or OS indication to be transmitted, and the individual channel circuits at station A should be set up.

Consider first that a lever, such as L, for station A was operated to a new position. This energizes the relay LV for that station. Then, as soon as the shaft 30 of the station selector assumes the half-step position, shown in Fig. 5, a test channel circuit through the test relay TS in the dispatcher's office for station A is established as follows:—starting at C, relay TS, wire 135, back contact 136, of channel circuit selecting relay 1, wire 137, back contact 138 of relay 2, wire 139, back contact 140 of relay 3, wire 141, back contact 142 of relay 4, wire 143, arm 41 on the shaft 30, to the signal line SGL, thence to station A, wires 112 and 144, finger 145 of the relay LR^a to the left, wire 146, back contact 142^a of channel circuit selecting relay 4^a, wire 141^a, back contact 140^a of relay 3^a, wire 139^a, back contact 138^a of relay 2^a, wire 137^a, back contact 136^a of relay 1^a, wire 147, and contact finger 148 of the relay 63 to B+ or B-, according to the position of this finger, and thence back to common.

The contact finger 145 of the relay LR is in the left or negative impulse position to complete the circuit just traced, since the stepping line circuit STL is energized negatively, as above explained.

On the assumption that a lever for station A had been operated to energize the relay LV, but

there had been no change in the track relay T at station A, the finger 148 of the relay 63 is in the lower position, energizing the relay TS over the test channel circuit just traced negatively to move the contact finger 150 of the relay TS to the left, whereupon with the lever relay LV energized, a circuit is established for energizing the channel impulse relay CI as follows:—starting at negative (—), relay CI, wire 151 to bus 152, wires 153 and 154, front contact 155 of the relay LV, wire 156, finger 150 of relay TS to the left, wires 157 and 158, arm 40 in the half-step position (see Fig. 5) to positive (+).

If it should happen that there had been a change in the condition of the track relay T at station A, subsequent to the last clearing out of the channel circuits at station A, then the finger 148 of the relay 63 would be in the upper position, energizing the relay TS positively, and thereby energizing the relay CI directly over wire 159, independently of the position of the contact 155 of the relay LV.

Thus, whether there is a new lever operation, or a change in the condition of the track relay T, for station A, the channel impulse relay CI is energized. This relay CI, when energized, is maintained energized by a stick circuit individual to each station, which may be traced from negative (—), relay CI, wires 151, 160, front contact 161 of relay CI, to bus 162, thence over wire 163, back contact 164 of the channel circuit selecting relay 4, wires 165 and 166, contact finger 167 of the circuit controller K in the normal position, wires 168 and 158, and arm 40 to positive (+). In this way, the relay CI is maintained energized until the last channel circuit selecting relay, which as shown is relay 4, is energized, or in other words until the necessary number of stepping impulses have been applied to the stepping line STL to operate all of the channel circuit selecting relays.

Any suitable means may be employed to apply positive and negative impulses to the stepping line STL, upon energization of the relay CI. As shown, the energization of the relay CI and the closing of its front contact 170 energizes the relay 48 through the back contact 171 of the slow acting relay 49, and the closing of the front contact 172 of the relay 48 energizes the slow acting relay 49. After a time, sufficient for the slow acting relay 49 to attract its armature, its contact finger 123 is raised to the upper position, applying a positive impulse to the stepping line STL through the line relay LR in the dispatcher's office and through the line relay LR^a at station A, or such other station as may then be selected. As soon as the armature of the slow acting relay 49 is attracted, the contact finger 171 de-energizes the relay 48, which in turn opens its front contact 172 and de-energizes the relay 49. After an interval of time required for the relay 49 to retract its armature, its finger 123 drops and applies a negative impulse. This same operation of picking up and dropping of the relays 48 and 49 continues and applies alternate positive and negative impulses to the stepping line STL, until the relay CI is de-energized, whereupon the relay 48 can not again pick up upon dropping of the relay 49.

Channel circuit selection.—The alternate positive and negative impulses impressed upon the stepping line STL cause the contact fingers 115 of the line relay LR in the dispatcher's office, Fig. 1B, and the contact fingers 176 of the line relay at the station then in communication with 75

the dispatcher's office, as the line relay LR^a for station A, to shift back and forth from one extreme position to the other, the position to the right being, for convenience, assumed to correspond with a positive impulse. These two contact fingers 115 and 176 of these two line relays are thus operated synchronously, since the relays are connected in series in the stepping line circuit, and have the current built up in their windings at the same rate, irrespective of the length of the line circuit.

The movement of these contact fingers 115 and 176 back and forth is used to energize sequentially the relays 1-4 and 1^a-4^a, which operate their corresponding contact fingers simultaneously and synchronously, so as to set up in rapid sequence a series of channel circuits for the transmission of the desired controls and indications. The control circuits for these channel selecting relays 1-4 and 1^a-4^a are the same, and a description of these circuits for the relays 1-4 in the dispatcher's office will be sufficient.

Back and forth movement of the contact fingers 115 of the relay LR alternately connects (+) to the two bus wires *a* and *b*. A positive impulse on the stepping line circuit energizes the bus *a*, and negative the bus *b*. The first impulse on the stepping line circuit, upon energization of the channel impulse relay CI is positive, due to the energization of the relay 49. This first positive impulse energizes the upper winding of the relay 1 over a circuit which may be traced from bus *a*, wire 181, upper winding of relay 1, wires 182, 183, 184 and 185, back contact 186 of the relay 4, wire 187, to arm 42 of the station selector shaft 30 in the position corresponding to station A and thence to (-). Although the bus *a* is connected to the upper windings of the relays 1 of the other groups of channel selecting relays for the other stations, the relay 1 for station A is the only one which is energized because the energizing circuit for the other relays 1 is broken at the arm 42.

The relay 1, when thus energized by the first positive impulse on the stepping line circuit, is maintained energized by a stick circuit through its lower winding from (+), through its front contact 188, wire 189, lower winding of relay 1, wire 190, to wire 183, and thence to (-) along the same path through the back contact 186 of relay 4 above traced.

On the next negative impulse, the bus *b* is energized, and this energizes the upper winding of the relay 2 over wire 191, front contact 192 of relay 1, wire 193, upper winding of relay 2, and wires 194 and 195 to wire 184 and thence to (-) over the same path above traced. The relay 2, when thus energized, is stuck up through its front contact 196 the same as the relay 1.

The next positive impulse, energizing bus *a*, energizes the upper winding of the relay 3 over wire 197, front contact 198 of relay 2, wire 199, upper winding of relay 3, and wires 200 and 201 to the wire 185 and thence to (-). The relay 3 is similarly stuck up through its front contact 202.

Upon the next negative impulse, energizing the bus *b*, the relay 4 is energized over wire 203, front contact 204 of relay 3, wires 205 and 206, relay 4 direct to negative (-). The relay 4 is stuck up through a circuit which may be traced from negative (-) through relay 4, wires 206 and 207, front contact 208 of relay 4, wires 209 and 166, contact finger 167 of switch K in the normal closed position, wires 168 and 158 to arm 40, in the station A position, to plus (+).

Upon energization of the relay 4, the opening of its back contact 186 de-energizes the relays 1, 2 and 3. The energization of the relay 4 also breaks at its back contact 164 the stick circuit for the channel impulse relay CI, so that the 5 impulses on the stepping line cease.

In this way, the channel circuit selecting relays 1-4 are energized sequentially one at a time. The same operation of the relays 1^a-4^a at station A takes place, except that the relay 4^a at the 10 station is stuck up through its front contact 208^a, wire 211, through the contact fingers 212 of the transfer relay TR, which is then in its negative or dotted line position as shown in Fig. 4, as a result of the sectionalizing negative impulse, as 15 hereinbefore explained.

It should be understood that any desired number of channel circuit selecting relays may be employed by extending or duplicating the control circuits as shown for the relays 1-4, the last 20 relay of the series being stuck up in the same way as the relay 4. The number of relays required would depend upon the number of channel circuits required for the corresponding station.

Any desired control or indication may be transmitted over any one of the several channel circuits set up by the channel circuit selecting relays. These channel circuits may be energized with alternating current or direct current of different polarities from sources either in the dispatcher's 30 office or at the station. As shown, the channel circuits are employed to transmit positive or negative direct current impulses to operate dead-beat polar relays, but obviously other arrangements could be employed.

As typical of a channel circuit for transmitting an indication from the station to the dispatcher's office, assume that the track relay T at station A (see Fig. 2A), is de-energized by the presence of the train on the corresponding detector track 40 circuit, and that the relay 62 is also energized. Then, when the channel circuit selecting relays 1 and 1^a are energized by the first positive impulse, a channel circuit for energizing the OS relay 7 for station A in the dispatcher's office is established and may be traced as follows:—starting at B+, front contact 214 of relay 62 (see Fig. 2A), wire 215, front contact 136^a of the relay 1^a, wire 137^a, back contact 138^a of relay 2^a, wire 139^a, back contact 140^a of relay 3^a, wire 141^a, back contact 142^a of relay 4^a, wire 146, contact finger 145 of relay LR^a, now to the right (positive impulse position), wires 216 and 112 to the signal line SGL thence to the dispatcher's office (see Fig. 1B), to arm 41 of the station selector shaft 30, 55 in its position corresponding to station A, wire 143, back contact 142 of relay 4, wire 141, back contact 140 of relay 3, wire 139, back contact 138 of relay 2, wire 137, front contact 136 of relay 1 (now energized), wire 217 (Fig. 1B) to wire 217 of 60 Fig. 1A, OS relay 1 to the common wire C, and thence back to the neutral terminal of batteries 53 at station A (see Fig. 2A).

Current flowing over this OS channel circuit, being of positive polarity, due to the energization 65 of the relay 62, shifts the contact finger 8 of the OS relay 1 to the dotted line position, energizing the OS lamp 6 intermittently in the manner previously explained, until this indication is recognized by the dispatcher and button 18 is operated 70 to cause the lamp to burn steadily with reduced brilliancy.

The condition of other track circuits, the position of switches or signals, or any other desired information may be transmitted from a station 75

to the dispatcher's office in a similar way over a channel circuit.

As typical of the operation of transmitting a control from the dispatcher's office to station A, assume that the lever L (see Fig. 1A) is operated to the other position. Then, upon energization of the channel circuit selecting relays 2 and 2^a, a channel circuit, similar to the one above traced, is set up from (B-) over wires 218 and 219 (see Fig. 1A) to the front contact 138 of the relay 2, thence through the back contacts 140 and 142 of the relays 3 and 4 to the signal wire, to station A through the contact fingers 145 of the line relay LR^a (now in the left or negative position), through the back contacts 142^a and 140^a of the relays 4^a and 3^a, through the front contact 138^a of relay 2^a, wire 220 to the polar relay 58 and thence to C. This channel circuit being energized negatively, causes the contact finger of the relay 58 to be shifted to the other position, and in turn operating the switch machine (not shown) to the other position.

In a similar way, the relays 59 and 60 at station A, (see Fig. 2A), may be operated to one position or the other by the movement of the lever LS (see Fig. 1A), so as to permit one of the signals 55-57^a to clear, subject to the presence of trains ahead, dependent upon the position of the switch and the direction of traffic set up by the extreme position to which the lever LS is shifted. Any desired number of switches, signals, derails, or other traffic controlling devices may be controlled by the dispatcher at any given station in a similar way.

Transfer to the next station.—After the channel circuits have been set up for station A, as just explained, and upon energization of the last relay, as 4, of the group or bank of channel circuit selecting relays for station A, current is applied through the front contact 164 of relay 4 over wire 210 to the bus 129, so as to energize the stepping magnet 36 and cause the station selector shaft 30 to advance another half-step to the position where the arms 40, 41, 42 and 43 break contact, and the arm 44 makes contact.

Under these conditions, a positive impulse from B+ is transmitted over arm 44, wire 178 through the transfer relay TR in the dispatcher's office and through the transfer relay TR^a at station A (see Fig. 2A). This positive impulse shifts the contact fingers 120, 212 and 110 of the transfer relay TR^a from the left hand position shown in Fig. 4 to the right hand position shown in Fig. 2A. This movement of the contact finger 120 breaks the energizing circuit for the upper winding of the transfer stick relay TRS, but so long as this positive impulse exists, the contact fingers of this transfer relay TRS are held in the raised or attracted position by the flow of current over wires 74 and 221, through the lower winding of this relay TRS, wire 222, and through its front contact 70 to C. After a time interval, sufficient for proper response of the transfer relay TR^a at station A, slow acting relay 51 in the dispatcher's office closes its front contact 223 and energizes the stepping magnet 37, thereby advancing the shaft 30 a half-step, so as to break contact at the arm 44, and bring the other arms 40, 41, 42 and 43 into their contacting position for the next station B.

When the arm 44 breaks its contact, the positive impulse on the transfer line TRL ceases, and the transfer stick relay TRS at station A (Fig. 2A) releases its armature and allows its contact fingers to drop. The contact finger 71 of this

relay TRS completes the transfer line circuit TRL over to station B, and the contact finger 72 connects the stepping line circuit STL to the line relay LR^b at station B.

Communication is now established between the dispatcher's office and the next station B; and as soon as the stepping line circuit, including the line relay LR in the dispatcher's office and the line relay LR^b in station B, is established, the negative impulse on this line circuit, supplied through the back contact 123 of the relay 49 causes the contact fingers of these two line relays to assume the left hand or negative position, whereupon a test circuit, similar to the one hereinbefore traced for station A, is set up. If the relay 63 at station B is energized, due to the picking up or dropping of the track relay T at station B since the last OS indication was transmitted, then the test relay TS in the dispatcher's office for station B is energized to shift the contact fingers 150 to the right, so as to energize the channel circuit impulse relay CI. Or, if any lever for station B has been operated to a new position, since the last clearing out of the control channel circuits, the relay LV for station B is energized. In this case, the channel circuit impulse relay CI is also energized. Thus, if there is a new control or OS indication for station B to be transmitted, then the energization of the relay CI applies alternate positive and negative impulses to the stepping line circuit and operates the channel circuit selecting relays, such as 1-4, at stations B and at the dispatcher's office, so as to set up a series of channel circuits for transmitting such new indication or control.

Skipping stations.—If it should happen that there has been no change in the position of the levers for station B, and no change in the condition of the track relay T at station B, then the test relay TS for station B in the dispatcher's office is energized with a negative impulse and its contact finger 150 assumes the left hand position, and also the relay LV in the dispatcher's office for station B is de-energized, so that current is supplied to the stepping magnet 36 over wire 224 to advance the shaft 30 another half-step, without time being taken to set up the individual channel circuits for station B. This applies to all of the other stations in the same way.

This automatic holding or skipping of stations is an important feature of the invention. In the first place, the channel circuit selecting devices are not operated unless required for the transmission of new indications or controls so that unnecessary wear on the parts is avoided. Furthermore, the time required to set up the channel circuits, not needed to transmit a new control or indication, is avoided, so that the total time cycle for scanning, so to speak, the whole controlled territory is greatly reduced, and makes it possible to have a greater number of channel circuits on a single set of line wires, or increase the time for setting up each channel circuit, without obtaining objectionable or prohibitive delay in the transmission of controls or OS indications.

To appreciate the significance of this feature of the invention, it should be understood that, under normal operating conditions and for such density of traffic and train movement ordinarily encountered in practice, particularly over an extended territory of a single track railroad, it is very rare that, within a given period of a few seconds, there would be any new control or OS indication to be transmitted from more than about one station out of eight or ten. For ex-

ample, in an installation for twenty passing sidings, under what can be termed normal or average operating conditions, it is rare that trains would happen to enter or leave track sections at the ends of more than two of these passing sidings exactly simultaneously, or within a limited period of a few seconds, or that the dispatcher will find it necessary to operate a switch or signal, within the same given period, at more than one or two siding ends. In other words, out of all of the channel circuits for the control territory under the supervision of the dispatcher, during a given period, it may be fairly assumed that, most of the time at least, only some ten per cent of the total channel circuits are actually required for the transmission of a new control or indication; and by eliminating the time required to set up the channel circuits not needed, it will be evident that the efficiency of the communication system is greatly increased.

This may perhaps be made clearer by a specific example. Assume, for instance, a single track installation of twenty passing sidings, with a station at each siding end, or a total of forty stations. It is found that it takes about one-fifteenth of a second to set up and utilize a channel circuit. The transfer from station to station may be made effectively in about the same time. It would require, therefore, let us say, about one-eighth of a second to select the station and set up the test circuit, making a total time of about five seconds to select and test out all of the forty stations. Assuming each siding end or station requires four channel circuits, if the channel circuits for only ten per cent of the stations have to be set up, then the additional time for channel circuit selection is about one second, making the total time cycle something in the order of six seconds. On the other hand, on the same assumption of four channel circuits per station, forty circuits per station and a fifteenth of a second for each channel circuit, the additional time required, if all of the channel circuits were set up, would be over ten seconds, making the total time cycle a matter of fifteen or more seconds. Thus, it might happen that, after a lever had been moved, or a track relay had changed, there would be a delay of some fifteen seconds before there would be any response in the field to such lever movement or indication in the dispatcher's office of change in track circuit conditions. In many cases, such a delay would very seriously handicap a dispatcher and interfere with the expeditious and efficient movement of trains. This would be particularly true in the case of a non-stop meet, or similar traffic congestion at a particular point or zone.

Completing station selection.—The same steps of transferring from station to station, establishing the test circuit, and setting up the individual channel circuits for such stations as may be required, as above explained, continues until the last station Z (see Fig. 2B) is reached. After the setting up of the individual channel circuits at this last station Z, or after response of the test relay TS for that station, indicating no need for the individual channel circuits, the stepping magnet 37 is energized in the same way previously explained, to advance the shaft 30 from the position corresponding to station Z one half-step, bringing the arm 43 into the position, one-half step short of its initial position, and establishing a circuit over wires 226 and 227 to energize the transfer line TRL and the relays TR at the several stations, without energizing the relay TR

in the dispatcher's office. Also, the arm 42 in this last half-step position establishes a circuit to energize the slow pick-up relay 230, which closes its front contact 231 after a time and energizes the bus 129 for the stepping magnet 36, so that the shaft 30 completes its last half-step and reaches its initial position shown in Fig. 1B. The time required for the relay 230 to close its front contact 231 is so selected that the shaft 30 remains in this last half-step position, and the transfer relays TR at the several stations are maintained energized positively, for a period of time long enough to cause the slow relay SL in the several stations to pick up their armatures. These slow relays SL, when thus picked up, are stuck up through their front contact 66, wire 67, lower winding, wire 68, and back contact 69 of the corresponding relay TRS, as shown in Fig. 2A.

Thus, at the end of each revolution of the shaft 30, a long positive impulse is applied to the transfer line TRL to pick up the slow relay SL at the several stations. With the slow relay SL at each station energized, and the contact 110 of the relay TR at that station in the right or positive impulse position, the circuit at that station for starting the system into operation is made up, so that when the relay 63 at that station is energized, the upper winding of the starting relay ST in the dispatcher's office is energized. The branch circuit at each station for starting the system into operation is broken at once at the contact 110 of the relay TR by the negative sectionalizing impulse on the transfer line TRL, and is maintained broken at the front contact 108 of the relay SL at that station, until the next long positive impulse is transmitted at the end of the revolution of the shaft 30. In this connection it should be understood that the positive impulses applied to the transfer line TRL over arm 44 to transfer a communication from station to station, are not long enough to energize the slow relays SL at the several stations.

After the shaft 30 assumes its initial position, as just explained, the system is ready for another operation. The transfer line TRL is completed through the several stations, so that when the starting relay is energized and the shaft 30 advances one-half step, the first negative impulse on the transfer line TRL sectionalizes the system, as hereinbefore explained, and at the same time de-energizes the slow relays SL at the several stations to open the starting circuits at all of the stations.

When the shaft 30 of the station selector reaches its initial position after a revolution, it may stay there until the system is set into operation at some subsequent time, or another revolution of the shaft 30 may be at once started, in a manner which will now be explained.

Clearing out of the channel circuits.—It will be evident that, during this cycle of operation of the system, while communication was set up between the dispatcher's office and some intermediate station, a lever might be operated, or a track relay dropped, at some one or more of the stations which had already been selected and at which the individual channel circuits might have been set up. Consequently, if the system should stop at the end of this first cycle or revolution of the station selector, there could be some control or indication which had not been transmitted, and would not be transmitted until the system was again set into operation by some new lever movement or change of a track relay.

For these reasons, it is important to organize

the system so that, when once set into operation, it continues in operation until all of the controls or indications have been cleared out, so to speak. There are several possible contingencies or cases 5 to be considered in this connection.

Assume first that, after the system had passed on to an intermediate station, say station B, a lever is operated for some preceding station, say station A, or the track relay T at some preceding 10 station, as station A, has either dropped or picked up due to a train movement occurring subsequent to the selection of that station. When such a new lever movement for station A occurred, the relay LV for that station was energized, and stuck up through its stick circuit. In the case of a change in the track relay T at station A (see Fig. 2A), the relay 63 would be energized through the make-before-break contact 95 of the relay 62, whether that relay was 15 energized or deenergized by the change in the track relay T; and the relay 63 will be stuck up through the back contact 103 of the relay 3^a.

When the system completed its cycle of operation under consideration, and the shaft 30 assumes 20 its initial position shown in Fig. 1B, the starting relay ST would be energized in either case, in the same way as hereinbefore explained in connection with the starting of the system from rest. Consequently, another revolution of 25 the shaft 30 would occur. In this way, the shaft 30 continues to rotate until, upon reaching its initial position, all of the lever relays LV are deenergized, indicating that no lever has been operated since the transmission of controls had 30 been completed, and until the relays 63 at all of the stations are de-energized, indicating that no change in track circuit conditions has taken place since the OS indications were last transmitted.

Another contingency is that a lever may be operated for a station while the channel circuit selecting relays are operating, and subsequent to the setting up of the channel circuit for that particular lever. To illustrate, referring to Figs. 1A 40 and 1B, suppose that, after the relay 3 has operated, to break at its back contact 140 the channel circuit over wire 219 to the lever L, this lever is shifted to a new position. It will be evident, that in such a case, it would be necessary to set up 45 again the channel circuits for station A, in order to transmit the new control. For this reason the stick circuit for the lever relay LV is so organized that it is broken, to permit de-energization of the relay LV, at the back contact 84 of the relay 1, when that relay is energized, and before the relay 50 2 is energized. As soon as the relay 2 is energized, then the stick circuit for the relay LV is completed through the front contacts 84 and 86 of the two relays 1 and 2, with the result that the movement of any lever thereafter would be registered, so to speak, by the energization of the relay LV. The relay LV is made slightly slow releasing, so 55 that if energized, with the 1 and 2 up, it does not drop during the momentary opening of its stick circuit upon simultaneous dropping of the contact fingers 84 and 86 of the relays 1 and 2, which occurs when the relay 4 picks up. Since the energization of the relay LV, as above explained, assures another revolution of the station selector shaft 30, the channel circuits for the station A under consideration are again set up, and the control corresponding to the operation of the lever L under consideration is transmitted in the regular way.

A similar contingency may arise in connection

with the dropping or picking up of the track relay T at a station. Considering station A, Fig. 2A, the track relay T may happen to pick up or drop, depending upon the movement of the trains into and out of the corresponding detector track circuits, at any time in the operation of the channel circuit selecting relays 1^a—4^a. The OS channel circuit is established through the front contact 136^a of relay 1^a, and is broken through the back contact 138^a of relay 2^a. Since the OS indication 10 can not be transmitted except while this OS channel circuit is set up, and since the train may enter or leave the detector track circuit at any time, it is necessary to make special provisions to assure the transmission of the OS indication.

For one thing, the train may enter the track circuit and drop the track relay T, and again leave the track circuit and permit the track relay T to pick up, before the OS channel circuit is set up, as for instance, while the system is operating 20 at some other station or stations. This condition is likely to happen with short fast moving trains or single locomotives or motor vehicles.

For this reason, provision is made by means of the relays 62 and 63 to store up, so to speak, the 25 OS indication that the track relay T has dropped, until such indication is actually transmitted to the dispatcher's office. When the track relay T drops, the relays 62 and 63 are picked up and stuck up in the manner previously explained, and 30 remain stuck up even after the train leaves the track section and the track relay T picks up. With the relay 63 energized, the closing of its front contact 106 assures starting of the system, if at rest, or another revolution of the station selector shaft 30, if the system is operating. Also, the closing of the front contact 148 of the relay 63 35 assures that a positive impulse will be transmitted over the test circuit to assure that the individual channel circuits will be set up for the station in 40 question when next selected, so as to transmit an OS indication. Upon operation of the channel circuit selecting relays at the station in question, when the relay 3^a picks up, it breaks at its back contact 103 the stick circuit for the relay 63, which 45 releases its armature. As soon as the relay 4^a picks up, the stick circuit for the relay 63 is again established over another branch through the front contact 105 of the relay 4^a.

When the relay 63 drops, it breaks at its front 50 contact 97 the stick circuit for the relay 62, and if the train has left, the relay 62 is de-energized. This relay 62, however, is made slightly slow acting so that, during the very short interval between the breaking of one stick circuit for the relay 63 55 at the back contact 103 of the relay 3^a and the making of another branch of the stick circuit at the front contact 105 of the relay 4^a, the relay 62 will not release its armature, and will thereafter, by closing its make-before-break contacts 95, 60 again energize the relay 63 momentarily and permit it to be stuck up. With the relay 63 thus energized, another operation of the channel circuit selecting relays 1^a—4^a is assured to transmit an indication that the track circuit is unoccupied, 65 the relay 62 being de-energized.

If at the time of the channel circuit selection for the station in question, the train is still on the detector track circuit and the track relay T is still shunted, upon de-energization of the relay 63, as 70 just explained, it remains de-energized until such time thereafter as the track relay T may pick up, whereupon the same energization of the relay 63 occurs, and the same subsequent operation of the channel circuit selecting relays 1^a—4^a, to trans- 75

mit an indication that the track circuit has become unoccupied.

If it should happen that the track relay T at station A (see Fig. 2A) should drop during the short time the relays 1^a—4^a are operating, and after the OS channel circuit is broken by the energization of the relay 2^a, the relay 63 is picked up and stuck up in the same way, and assures a subsequent cycle of operation of the system.

For these reasons, the system, when once set into operation, continues to operate until all new controls or indications have been transmitted. During the transmission of a new control or indication for any given station, all of the other controls or indications for that station are repeated, since all of the individual channel circuits for that station are set up. This gives a check on conditions at that station. This checking feature aids greatly in avoiding continued or persistent false indication or control, as may happen in other types of communication systems, such as the code type, where a control or indication is transmitted only once and is not automatically checked until repeated or changed. The dispatcher is able to obtain such check of the conditions at any station by moving any lever for that station over to a different operated position and back again, the relay LV being energized by such lever movement, and causing the channel circuits for that station to be set up, also starting the system into operation, if necessary. If desired, a special key may be provided to enable the operator to energize at will the relays LV for all the stations, so that he is able to check all of the controls and indications, without making a special lever manipulation for each station.

Manual station selection.—Under practical operating conditions, such as in making a non-stop meet, it is often important that the dispatcher should obtain an OS indication of the entrance of a train into certain track sections as quickly as possible, and should also be able to secure prompt operation of a switch or signal in response to a lever movement. The dispatcher is ordinarily able to determine ahead of time the particular siding, or other control point or zone, where train movements are next likely to occur which would necessitate prompt operation of switches and signals, since he is kept informed of the train positions by the OS indications, and knows the running time of the trains from point to point.

Although the automatic skipping of stations, as above explained, helps greatly in shorting the total time cycle of operation of the system, and aids in obtaining prompt response to track relay changes or lever operations, there are critical times when the dispatcher is not at all interested for the time being in OS indications from the various points along the track, where trains may enter and leave track sections, and would be assisted in handling the traffic at some congested point, if such unimportant OS indications were discontinued, and the communication system localized, so to speak, to the particular station in which the dispatcher is then interested.

For these reasons, the system of this invention is preferably organized so that the dispatcher may, by a simple manual manipulation, confine the channel circuit selection to some selected station for such period of time as he may elect. As illustrative of this operation of manual station selection, assume that the dispatcher wishes to confine his attention for a while to station A. To do this, he operates the key K, Fig. 1B, corre-

sponding to station A, and moves either the lever L or the lever LS to a new position and then returns such lever to its former position, which operation is for momentarily closing the pick-up circuit of the relay LV, as previously described. 5 The movement of the contact finger 167 of key K, from the position shown to the other extreme position, establishes a circuit for energizing the relay LV for station A from plus (+), arm 40, wires 158 and 168, fingers 161, wires 233 and 80, 10 relay LV to negative (-), when the selector SS has been operated to select the station A. If the system is at rest, this energization of the relay LV starts it into operation. If the system is running and has passed the station in question, it completes another cycle of operation. In either case, upon coming to station A, the relay CI is energized, since the relay LV for station A is picked up, and the channel circuits for station A are set up. When the last relay, as 20 4 is energized, the closing of its front contact 164 does not energize the stepping magnet 36, because the finger 167 of the key K is shifted. Similarly, the stick circuit for relay 4 is not established, and as soon as the negative impulse 25 on the stepping line circuit (which causes energization of the relay 4) ceases, this relay drops, making the bank of relays 1—4 ready for another operation. Since the relay LV is held up through the key K, the relay CI is again energized, and the stepping impulses are continued. 30

In order that the relays 1^a—4^a at station A, referring to Fig. 2A, may be operated the second time, it is necessary to break the stick circuit for the relay 4^a through the contact finger 212 35 of the transfer relay TR^a, which is in its negative or dotted line position, since the system is sectionalized and station A selected. This is done by applying a positive impulse to the transfer line TRL over a circuit from (B+), arm 43 of the 40 shaft 39 in the station A position, wire 234, holding coil 235, finger 236 of key K (now closed), and wire 237 to the transfer line TRL. This circuit energizes the transfer relay TR^a at the station A, and all of the other relays for other stations 45 nearer the dispatcher's office, but does not energize the transfer relay TR in the dispatcher's office. This causes the contact finger 212 of the transfer relay TR^a at the station selected to move to the right or positive impulse position (these 50 relays for stations near the dispatcher's office being already in that position), and break the stick circuit for the relay 4^a, so that the relays 1^a—4^a may be repeatedly operated to set up the 55 channel circuits for that particular station sequentially as long as the key K is operated.

Thus, the dispatcher may select manually any station at which he desires the channel circuits to be set up continuously, and it is evident that any change in the condition of the track relay at 60 that station will be practically instantaneously transmitted to the dispatcher's office, and similarly the signals and the switch at that station respond very quickly upon movement of a lever in the dispatcher's office, since all of the channel circuits for one station may be set up in a second or less. Consequently, the dispatcher is able to put himself in direct and practically instantaneous communication with any station he desires, and is able to handle traffic at that station very 65 expeditiously.

When the dispatcher is through with the station he has selected manually, he restores the key K to the normal position. This sets up the normal operating conditions, so that, when the last 70 75

- relay 4 of the group of channel circuit selecting relays has operated, this relay is stuck up, the stepping magnet 36 is energized, the relay CI is de-energized, and the shaft 30 advances a half-step to the position to transfer to the next station. In order to avoid an interruption in the positive impulse on the transfer line TRL, the continuance of which prevents the transfer from the next station by keeping the lower winding 5 of the transfer stick relay TRS energized, the holding coil 235 is provided, and the contacts for the arm 43 are extended, so that positive current on the transfer line TRL is maintained through the arm 43, holding winding 235 and contact finger 236 until the arm 44 has supplied the positive current to the transfer relay TR in the dispatcher's office, and through the operation of the relay 51 has energized the stepping magnet 37 to advance the shaft another half step to the position corresponding to the next station, which is automatically selected as soon as the positive impulse applied over wire 237 ceases. In this connection, it should be understood that the button or plunger of the key K, when retracted to 25 the normal position, does not open the contact finger 236, but merely releases it, so that it will open upon de-energization of the holding coil 235, which occurs when the arm 43 is moved off of the contact for the station in question.
- 30 Following such release of the key K by the dispatcher, and the automatic transfer to the next station, the system then continues in operation in the regular way until all new OS indications or controls have been transmitted, and all of the 35 channel circuits have been cleared out, as hereinbefore explained. During this operation, such trains as may have entered track circuits in the meantime are reported by the lighting of the corresponding OS lamps; and if these trains have left their respective track sections, during the next cycle of operation, these lamps are extinguished. By watching the track diagram, therefore, the operator is able to bring himself up to date, so to speak, with respect to train movements that occurred while he was confining his 40 attention to a selected station.
- While for convenience a station has been referred to as comprising one siding end, it is often desirable to include both ends of a passing siding, and perhaps more switches and signals, as 45 a single station which the operator may manually select; and on account of the economy in wiring connections, it may be expedient to locate line relays and channel selecting relays, such as 50 1^a—4^a, at different points along the track, and operate them simultaneously as one station equipment. This is readily accomplished by using enough channel selecting relays to take care 55 of the channel circuits required for both ends of the passing siding, or such other territory as may constitute the station, and duplicating the transfer and line relays and other devices at these locations to obtain simultaneous operation of these banks of channel circuit selecting relays, in 60 a manner which will be readily apparent from a consideration of the circuits shown and the foregoing explanation of the operation.
- 70 *Automatic synchronization.*—The groups or banks of channel circuit selecting relays are automatically stopped, unless the corresponding key K is operated, at the end of each operation. When the last relay of the bank in the dispatcher's office for each station, as 4, picks up and is stuck up, as previously explained, its back contact 75 186 opens the energizing circuits for the

upper windings of the preceding relays, as 1, 2 and 3. The same is true for the relays 1^a—4^a at the corresponding station. Consequently, any extra impulses on the stepping line circuit, due to inductive surges, or other causes, do not operate these selecting relays any further, either in the dispatcher's office, or at the station then selected.

In this way, the two banks of channel circuit selecting relays, one at each station, and a corresponding one in the dispatcher's office, are automatically maintained in synchronism. Stepping impulses are transmitted until the last relay, as relay 4, operates; and any extra impulses have no effect. On the other hand, if an impulse should be skipped, either in the dispatcher's office, or at a station; and hence at the end of the series of impulses, all of the relays of either bank have not responded, as they should have done, the next time the stepping impulses are applied to the stepping line STL, the remaining relay or relays of the bank, which have not previously responded, are operated and then further operation of the relays of that bank ceases, so that on the next series of stepping impulses the two banks of relays start off together in step.

This feature of automatic synchronization has been shown for the purpose of correcting extraneous and transient impulses on the stepping line circuit, which may cause the two corresponding banks of relays to skip or gain a stepping impulse. Also, a bank of relays may be disconnected, to be repaired or replaced by a new set, and put back in the system, with the assurance that they will be automatically brought into step with the corresponding other bank of relays. If this feature, however, is not required, the stick circuits for the control of the relays 4 and 4^a may be omitted, such omission also making it possible to leave out the arm 43, holding coil 235 and contact finger 236 of the key K, which are employed merely to remove the stick circuit for the relay 4^a upon manual station selection.

Channel circuit isolation.—An important feature of the system is that communication is established between the dispatcher's office and one station at a time, and the channel circuits for the stations, both in the dispatcher's office and along the track, are not connected to the signal line SGL, except when that station is selected. In the dispatcher's office, the connection between the signal line SGL and the banks of channel circuit selecting relays for the several stations is made through the arm 41 on the shaft 30. At the stations, referring to Fig. 2A, the channel circuits are connected to the signal line SGL (excepting the starting circuit) over wires 144 or 216 and wire 146, only when the line relay LR for that station is energized; and since this line relay is connected to the stepping line STL only at the station then selected, only one line relay can be energized at a time. Consequently, any failure or derangement of the channel circuits, either in the dispatcher's office or at any of the stations, is limited to the particular station affected, and can cause false or improper control and indication only for that station. This is in marked contrast to selecting systems of the synchronous type, where the channel circuits are not so isolated, and where the failure in a channel circuit, by permanently applying current to the signal line, or connecting the signal line permanently to the common line, may cripple the whole system.

Line circuit failures.—In the system of this in-

vention, in the event of failure in the line circuits, or in the contacts of the transfer stick relay TRS, the system may be operated up to the point of break or failure, since the transfer relays are connected in multiple between the transfer line TRL and common, either through the upper windings of the relays SL and the back contact 70 of the relay TRS, as shown in Figs. 2A and 2B, or through the lower winding of the relay TRS and its front contact 10, as shown in Fig. 4.

On account of this multiple connection of the relays TR, and the fact that the number of relays across the transfer line TRL and common varies, the resistances 238 are preferably employed to vary the voltage impressed upon the transfer line in accordance with the position of the arm 44 and the number of relays TR to be energized.

In the case of such line wire or contact failure, 20 the system would stop, since the test circuits, which cause energization of the stepping magnet 36 and further movement of the shaft 30 could not be set up for the stations beyond the break or failure, on account of the channel circuit 25 isolation hereinbefore pointed out; and to keep the system running, connections would have to be made from the contacts of the arm 40 for the defective stations to the bus 129 for the stepping magnet 36, to take the place of those connections 30 established through the contacts 150 of the test relays TS, and the front contact of the relay 164 of the relay 4, of these stations. These connections may be made by emergency jumpers, or if desired, special switches might be provided for 35 the purpose of cutting out stations beyond such break or failure.

Considering that such line failure may occur while the station equipment is in the normal condition shown in Fig. 2A, leaving the starting 40 circuit set up, and making it possible, if the signal line SGL is intact, to cripple the whole system by leaving a connection between common and the signal wire over this starting circuit at stations beyond the break, it may be expedient to 45 omit the stick circuit through the lower winding of the relay SL, and maintain this relay energized, to keep the starting circuits at the several stations closed, by continuously energizing the transfer line TRL with positive current in the initial 50 position of the arm 43 (see Fig. 1B), with the system at rest. In that case, any failure in the transfer line circuit would allow the relays SL to drop and break all the starting circuits. The stick for the relay SL, as shown, is employed 55 merely to avoid such continued energization of the transfer line TRL with the system at rest; and in practicing the invention this stick circuit may or may not be used, as may be considered desirable.

60 *Modifications of transfer circuits.*—One characteristic feature of this invention is the scheme of station selection by using a transfer line circuit and transfer relay, as distinctive, for example, from the method of station selection by 65 simultaneously operated devices as disclosed in my prior application Ser. No. 348,336, filed March 19, 1929, now Patent No. 2,082,464, granted June 1, 1937. The transfer circuits may be arranged to accomplish this result in different ways; and 70 Figs. 6 and 7 show two modifications of such transfer circuits.

Referring to Fig. 6, the transfer relays at the stations are of the typical neutral-polar type, with a neutral armature 240 and three polar armatures or contact fingers 241, 242 and 250. The

system is sectionalized by a negative impulse the same as in the form shown in Figs. 2A, 2B and 4. This negative impulse through the transfer relays TR in multiple across the transfer line TRL and common, shifts the polar contacts 241 of all 5 the relays TR to the left and de-energizes the relays 243, so that the contacts 244 and 245 of these respective relays 243 interrupt the transfer line TRL and stepping line STL at the corresponding station, and connect the stepping line 10 STL to the line relay LR^a at the first station A nearest the dispatcher's office. Fig. 6 shows at station B this sectionalized condition.

When a positive impulse is applied to the transfer line TRL, in the manner previously explained, the polar contact 241 of the transfer relay TR^a at the station then in communication with the dispatcher's office is shifted to the right; and when this impulse ceases, and the neutral armature 240 of that transfer relay drops, an 20 energizing circuit for the relay 243 is established from (+) through the back contact 240 of the neutral armature, wire 246, polar contact 241 to the right, wire 247, relay 243, to negative (-). This energization of the relay 243 closes its front 25 contacts 244 and 245 to transfer to the next station. Also, the closing of the front contact 249 of the relay 243 closes a stick circuit for that relay over wire 248, polar contact 241 to the right, wire 247 and relay 243. This stick circuit keeps 30 the contacts 244 and 245 of the relay 243 closed upon subsequent positive transfer impulses. Fig. 6 shows at station A this condition of the parts and circuits. The relay SL, establishing the starting circuit, is energized through the front 35 contact 248 of the neutral armature of the relay TR and its polar armature 251 to the right (positive position) so that a long positive impulse held on the transfer line TRL picks up the relay SL and shifts the polar contact 242 to close the 40 starting circuit. No stick circuit for the relay SL is shown, and it is contemplated that the arm 43 in its initial position shown in Fig. 1B will keep the transfer line TRL energized positively.

Referring to Fig. 7, in this modification, the 45 transfer relays TR are also neutral polar relays with a neutral armature or contact finger 240 and three polar contact fingers 241, 242 and 250, the same as in Fig. 6. In this modification, the transfer line TRL is continuous, and the system 50 is sectionalized by short circuiting this transfer line to common, through wire 254 and front contact 255 of a stick relay 256. A negative sectionalizing impulse closes a pick-up circuit for the relay 256 through the polar contact 241, and 55 until an impulse of the opposite polarity is sent over the transfer line TRL the several relays 256 remain energized and the system is sectionalized. Upon the first positive impulse, to transfer from station A to station B, the polar contact 241 60 shifts to break this pick-up circuit for the relay 256, but this relay is maintained energized, so long as this positive impulse continues, by a stick circuit through a front contact of the neutral armature 240, wire 257 and 258, front contact 65 259 of the relay 256, wires 260 and 261, and relay 256. When this positive impulse ceases, the relay 256 is de-energized, and opens its front contact 255 to remove the shunt or short-circuit on the transfer relay as the next station further 70 from the dispatcher's office. At the same time, the front contact 262 of the relay 256 opens and disconnects the line relay LR at that station from the stepping line STL and passes on the stepping line to the next station. As shown at station B 75

of Fig. 7, the stepping line STL may also be made continuous and the contact 262 of the relay 256 employed to open and close a short circuit, instead of a break in the stepping line circuit. The 5 relay SL is energized in the same way as in the arrangement of Fig. 6.

Various other modifications, additions and adaptations may be made in the particular arrangement and construction of devices shown 10 and described without departing from the invention.

What I claim is:—

1. In a dispatching system for railroads, a dispatcher's office, a plurality of way stations, 15 traffic controlling devices at each station, selecting means at each station for establishing circuits for the control of the traffic controlling devices at that station, a stepping line circuit, a line relay at each station for operating the 20 selecting means at that station, a transfer line circuit for station selection, and means at each station responding to impulses applied to said transfer line circuit for connecting the line relays at the several stations one at a time to the 25 stepping line circuit.

2. In a dispatching system for railroads, a dispatcher's office, a plurality of way stations, a stepping line wire extending from the dispatcher's office along the track and divided into sections 30 terminating at said stations, selecting means at each station for governing the corresponding traffic controlling devices, a line relay at each station controlling the corresponding selecting means, a station selecting line circuit, 35 and means at each station responding to the number of impulses applied to said station selecting circuit for connecting together the sections of the stepping line wire at each station in turn one at a time.

3. In a dispatching system for railroads, a dispatcher's office, a plurality of way stations, selecting means at each station for governing the operation of the traffic controlling devices at 40 that station, a line relay at each station controlling said selecting means, a stepping line wire extending from the dispatcher's office along the railroad and divided into sections terminating at said stations, a circuit controller at each station in one position connecting together the sections of the stepping line wire at that station and in another position connecting the section 45 extending toward the dispatcher's office to the line relay at that station, a station selecting line circuit, and means at each station responding to the number of impulses applied to said station selecting line circuit for operating said circuit controller at that station to its other position.

4. In a dispatching system for railroads, a dispatcher's office, a plurality of way stations, a bank of neutral relays at each station, a stepping 60 circuit, means controlled from the dispatcher's office for connecting said banks of relays at the several stations to said stepping circuit only one bank at a time, means controlled by said stepping circuit for operating the relays of each bank sequentially one at a time, and means controlled by said bank of neutral relays at each station for governing the traffic controlling devices at that station.

5. In a dispatching system of the synchronous type, the combination with a dispatcher's office and a field station connected by a signal wire and a common wire, of a plurality of neutral relays, means for energizing said relays sequentially one at a time, and a plurality of channel

circuits established by the sequential energization of said relays across the signal wire and common wire, said channel circuits each including a front contact of one of said relays and back contacts in series of all of the relays of 5 said plurality subsequently energized, whereby the energization of a relay of said group breaks one channel circuit when it closes another.

6. In a communication system of the synchronous type for dispatching trains, a combination 10 with a dispatcher's office and a plurality of stations, of a bank of neutral relays at each station, banks of neutral relays in the dispatcher's office one bank for each station, station selecting means in part at said office and in part in 15 each of said stations for selectively connecting each bank of neutral relays in the dispatcher's office to the bank at the corresponding station one at a time, and other means for energizing the relays of two banks thus interconnected synchronously and sequentially one at a time. 20

7. In a system of the character described, a dispatcher's office, a plurality of stations, a bank of neutral relays at each station, corresponding banks of relays in the dispatcher's office one for 25 each station, a line relay at each station for energizing the corresponding bank of relays sequentially one at a time, a line relay in the dispatcher's office, and station selecting means for connecting the line relay in the dispatcher's 30 office with the line relay at each of the stations in turn one at a time and for rendering the line relay in the dispatcher's office effective to operate the bank of relays in the dispatcher's office corresponding to the station then selected. 35

8. In a dispatching system of the character described, station selecting means comprising, a station selecting line wire divided into sections, and means at each station responding to an impulse of one polarity on said line wire for 40 connecting together the sections of said line wire at that station upon cessation of said impulse.

9. In a dispatching system of the character described, a dispatcher's office, a plurality of stations, a station selecting wire extending from the dispatcher's office along the railroad, means at each station responding to an impulse of one polarity on said station selecting line wire for breaking said wire into sections terminating at 45 said stations, said means acting in response to an impulse of the opposite polarity received over said station selecting wire at the corresponding station to connect together the sections of said wire at that station upon cessation of that impulse. 50

10. In a dispatching system of the character described, a plurality of stations, a transfer line circuit, a transfer relay at each station, a stick relay at each station having contacts in said 60 line circuit and having a pick-up circuit, and means including said transfer relay for closing said pick-up circuit of said stick relay when said transfer relay is energized by current in said line circuit of one polarity.

11. In a dispatching system, a dispatcher's office, a plurality of stations, an impulse responsive line relay at each station, impulse means in the dispatcher's office, a stepping line circuit connected to said impulse means, a separate station selecting line circuit, and means controlled by said station selecting line circuit at each station for connecting the impulse responsive line relays at the several stations to said stepping line circuit only one 70 at a time. 75

12. In a dispatching system, a plurality of banks of channel circuit selecting relays in a dispatcher's office, a line relay in the dispatcher's office, and station selecting means for rendering said line relay effective to control the energization of the relays of said banks one at a time.
13. In a dispatching system, a dispatcher's office, a plurality of stations, a bank of channel circuit selecting relays at each station, station selecting means for operating said banks of relays at the several stations only one at a time, manually operable levers in the dispatcher's office for each station, and means responsive to a change in the position of the levers associated with each station for governing the operation of said station selecting means.
14. In a dispatching system, a dispatcher's office, a plurality of stations, station selecting means including a line circuit extending to the several stations for establishing communication between the dispatcher's office and the several stations only one at a time, said means being normally inactive in an initial condition, a device in the dispatcher's office for starting said means into operation, and means controlled over said line circuit for establishing partial circuits at each station for the control of said starting device.
15. In a dispatching system for railroads, a dispatcher's office, a plurality of way stations, a stepping circuit connecting the dispatcher's office with the several stations, means for energizing said stepping circuit with impulses of different polarities, a bank of neutral stepping relays at each station, each stepping relay having a pick-up circuit controlled by the front contact of the next preceding relay in the bank, means controlled by impulses on said stepping circuit for alternately energizing the pick-up circuits for alternate stepping relays of said bank, a message circuit connecting the dispatcher's office and said stations, and means governed by said stepping relays for controlling the energization of said message circuit at successive time intervals corresponding with the energization of said stepping circuit.
16. In a dispatching system for railroads, a dispatcher's office, a plurality of way stations, traffic controlling devices, at each station, a control relay for each device, a stepping circuit connecting the dispatcher's office with the several stations, means in the dispatcher's office for energizing said stepping circuit with impulses of different polarities, a bank of neutral stepping relays at each station, means controlled by the impulses on said stepping circuit for energizing said stepping relays sequentially one at a time, and an energizing circuit for each of said control relays, each of said circuits including a front contact of one of the stepping relays and the back contacts in series of all of the relays in said bank subsequently energized, whereby the circuits for energizing said control relays are momentarily established by each impulse applied to said stepping circuit.
17. In a dispatching system for railroads, a dispatcher's office, a plurality of way stations, devices at each station having different operated conditions to be indicated in the dispatcher's office, a bank of neutral stepping relays at each station, means for operating said stepping relays sequentially, a message circuit extending from the dispatcher's office to the several stations, and means for rendering said devices at said stations effective only one station at a time to control the energization of said message circuit.
18. In a dispatching system for railroads, a dispatcher's office, a plurality of way stations, devices at each station having different operated conditions to be indicated in the dispatcher's office, a message circuit and a stepping circuit connecting the dispatcher's office to the several stations, means in the dispatcher's office for energizing said stepping circuit with time-spaced impulses, a bank of neutral relays at each station operated sequentially one at a time by the impulses of said stepping circuit, and means for rendering said devices at said stations effective only one station at a time to control the energization of said message circuit after each stepping operation of said bank of relays.
19. In a dispatching system for railroads of the type described, a dispatcher's office, a plurality of way stations, a plurality of traffic controlling devices at each station, line wires connecting the dispatcher's office with the several stations, banks of neutral relays in a dispatcher's office and at the several stations operating synchronously, and means including said banks of relays for transmitting controls over said line wires to the several traffic controlling devices as a group at said stations one at a time.
20. In a dispatching system for railroads, an indicating lamp in the dispatcher's office for indicating traffic conditions on said railroad, a control relay automatically assuming one position or another depending upon traffic conditions, a bus wire, means for intermittently energizing said bus wire, a manually controllable relay, a flashing circuit for said lamp closed by said control relay in said one position by connecting said lamp to said bus wire through a contact of said manually controllable relay and said circuit being open with said control relay in said another position, and another circuit for energizing said lamp steadily including a contact of said manually controllable relay closed when its first mentioned contact is open.
21. In a dispatching system for railroads, the combination with a control machine in the dispatcher's office having indication lamps signifying by their illumination the conditions of traffic on such railroad, means for automatically controlling said lamps to be energized or deenergized in accordance with the operated condition of corresponding traffic controlled devices along the railroad, a source of current, a bus wire, means for intermittently connecting said bus wire to one terminal of said source, and manually operable means for connecting each lamp to said bus wire or to said terminal of said source, whereby each lamp is lighted intermittently or steadily depending upon the operation of its said manually operable means and is entirely deenergized depending upon the operated condition of the corresponding traffic controlled device.
22. In a dispatching system for railroads, the combination with a track diagram depicting the actual railroad system and a plurality of lamps associated therewith to indicate the presence of trains on corresponding portions of the railroad, a bus wire, means for intermittently energizing said bus wire, means for connecting each lamp to said bus wire when a train is present on the corresponding portion of the track and thereby cause said lamp to be intermittently lighted, and manually operable means governed by said last mentioned means for causing said lamp to burn steadily only so long as the train is present on the corresponding portion of the track.
23. In a dispatching system for railroads, a

- dispatcher's office, a plurality of way stations, a stepping circuit connecting the dispatcher's office with the several way stations, means for energizing said stepping circuit with a plurality of impulses, a bank of neutral stepping relays at each station each stepping relay having a pick-up circuit controlled by the front contact of the next preceding relay in the bank, means controlled by the impulses on said stepping circuit for alternately energizing the pick-up circuits for alternate stepping relays of said bank, and stick circuits for each of said relays closed until the application of the last impulse of said plurality of impulses.
- 15 24. In a system of the character described, the combination of traffic controlling devices at a controlled location along a railway, a plurality of neutral stepping relays for controlling the operation of said traffic controlling devices, means for energizing said stepping relays sequentially only one at a time, a stick circuit for each of said stepping relays closed when such stepping relay assumes its energized position and means responsive to the picking up of the last of said stepping 25 relays for simultaneously breaking all of said stick circuits.
25. In a centralized traffic control system for railroads, a dispatcher's office, a plurality of field stations, two line wires interconnecting said dispatcher's office and said field stations, means at the dispatcher's office placing a plurality of series of impulses of one polarity across said two line wires, each series being preceded by a single impulse of the opposite polarity, and means at said plurality of stations for selecting said stations successively in response to the impulses of each series, said means at said stations being restored to normal by each of said single impulses of the opposite polarity.
- 30 26. In a centralized traffic control system for railroads, a dispatcher's office, a plurality of field stations, two line wires interconnecting said dispatcher's office and said field stations, means at the dispatcher's office placing a plurality of series of impulses of one polarity across said two line wires, each series being preceded by a single impulse of the opposite polarity, a polar relay at each of said stations, and means initially conditioned by said single impulse to render said polar relays successively responsive to the impulses of that series of impulses immediately following said single impulse.
- 35 27. In a centralized traffic control system for railroads, a dispatcher's office, a field station, a communication system connecting said dispatcher's office and said field station including a bank of neutral stepping relays at the control office and a bank of neutral stepping relays at said field station both of said banks capable of being operated sequentially and in synchronism, a plurality of control levers, a stick relay having a pick-up circuit momentarily closed upon the movement of any of said levers to a new position, said stick relay being capable of initiating said banks of neutral stepping relays when energized, and a stick circuit for said relay closed both when two successively operated stepping relays are deenergized and when said two relays are energized, whereby said stick circuit is open only between successive operations of said two relays.
- 40 28. In a centralized traffic controlling system for railroads, a plurality of field stations, a line circuit interconnecting said stations, a step-by-step selector control means at each station, a station selecting relay at each station for rendering

said step-by-step selector control means effective at the corresponding station, a pick-up circuit for each of said station selecting relays closed at the beginning of each station selecting cycle of operation of said system, means deenergizing said station selecting relays during a station selecting cycle in accordance with impulses placed on said line circuit, and a stick circuit for each of said station selecting relays for maintaining the particular one of said relays energized at the particular station which is selected.

29. In a dispatching system for railroads, an indicating lamp, an indication storing relay having a control contact operable to either of two positions, two energizing circuits for said indicating lamp closed with said contact in only one of its two positions, manually governable means when in one position closing one of said energizing circuits, means causing the established circuit to be intermittently closed, said manually operable means when in the other position establishing said other energizing circuit, and means maintaining said manually governable means in said other position dependent upon the flow of current in said other energizing circuit.

30. In a dispatching system for railroads, a dispatcher's office, a field station, a stepping circuit and a message circuit connecting the dispatcher's office and said field station, a bank of normally de-energized neutral stepping relays at said office and said field station, means for energizing said stepping relays sequentially one at a time in response to impulses applied to said stepping circuit, devices at said field station having different operated conditions to be indicated in the dispatcher's office, a plurality of circuits each including a front contact of one of the stepping relays in said bank at the field station and the back contacts in series of all of the succeeding relays in said bank, said circuits rendering said devices selectively effective to control the energization of said message circuits, and indication registration means in the dispatcher's office responding to the energization of said message circuit during the successive operation of said stepping relays.

35 31. In a system for governing traffic on railroads from a central office, a field station, a stepping circuit and a message circuit connecting the field station and the central office, normally inactive impulsive means in the central office operable to energize said stepping circuit with time-spaced impulses, a bank of normally de-energized neutral stepping relays at said central office and said field station, means for energizing said stepping relays in said banks sequentially one at a time and in synchronism in response to the impulses applied to the stepping circuit, a device at the field station having different operated conditions to be indicated in the central office, indication registration means in the central office, said banks of stepping relays acting to establish concurrently a circuit at the field station for rendering said device effective to control the energization of said message circuit and a circuit in the central office for rendering said indication registration means responsive to such energization of the message circuit, and means actuated by a change in the operated condition of said device for initiating the operation of said impulsive means.

36 32. In a dispatching system for railroads, a dispatcher's office, a field station, a stepping circuit and a message circuit connecting the dispatcher's

office and the field station, means in the dispatcher's office for energizing said stepping circuit with a predetermined number of time-spaced impulses, a polar line relay in said stepping circuit energized by said impulses, a group of normally de-energized neutral stepping relays having energizing circuits controlled by said line relay and each including a front contact of the next preceding relay, stick circuits for maintaining said stepping relays energized, means controlled by the last relay of said group for breaking said stick circuits, and a plurality of sequential circuits controlled by said stepping relays for governing the energization of said message circuit.

33. In a dispatching system for railroads, a dispatcher's office, a field station, a stepping circuit connecting the field station and dispatcher's office, normally inactive impulsive means in the dispatcher's office for energizing said stepping circuit with time-spaced impulses, a bank of normally de-energized neutral stepping relays at the dispatcher's office and at the field station, said stepping relays being controlled by said stepping circuit and being energized sequentially one at a time in response to said impulses, a plurality of devices at the field station to be controlled, channel circuits for said devices each including a front contact of one of said stepping relays and the back contacts in series of all of the other relays in said bank subsequently energized, control means in the dispatcher's office corresponding with said devices to be controlled at the field station, channel circuits for said control means each including a front contact of one of the stepping relays and the back contacts in series of all of the other relays subsequently energized, and means in the dispatcher's office for initiating the operation of said impulsive means and thereby cause operation of said banks of stepping relays to establish said channel circuits.

34. In a system for controlling railway traffic at a field station from a central office, a stepping circuit connecting the central office and the field station, normally inactive impulsive means in the central office for energizing said stepping circuit with time-spaced impulses, banks of normally de-energized neutral stepping relays energized sequentially one at a time in response to the impulses applied to the stepping circuit, said relays being maintained energized until the last relay of said bank has been energized, a plurality of circuits controlled by each bank of stepping relays, each of said circuits including a front contact of one of the stepping relays and back contacts in series of all of the relays in said bank subsequently energized, and manually controllable means responsive to the energization of the last relay in said bank at the central office for governing the operation of said impulsive means.

35. Remote controlling apparatus comprising an office and a series of remote stations, a control relay at each station, means controlled from the office for actuating the control relay at the first station of said series, means effective when any control relay is actuated for transmitting a signal between the corresponding station and the office, and means effective upon the completion of such signal to actuate the control relay for the next station in said series.

36. Remote controlling apparatus comprising an office and a series of remote stations, a control wire normally connecting said office and the stations of said series, a control relay at each station, means for actuating the control relay at each station over said control wire, means

effective when any control relay is actuated for transmitting a signal between the corresponding station and the office, and means effective upon the completion of such signal to extend the control wire to the next station in said series to actuate the control relay at such station.

37. Remote controlling apparatus comprising an office and a series of remote stations, a control wire connecting said office and the stations of said series, a second wire connecting all said stations with said office, a control relay at each such station, means effective when any control relay is actuated for transmitting a signal between the corresponding station and the office over said second wire, means for actuating the control relay at the first station of said series over said control wire, and means effective upon the completion of each said signal over said second wire to extend said control wire to the next station in said series beyond the station at which the control relay was actuated to initiate such signal.

38. Remote controlling apparatus comprising an office and a series of remote stations, a control relay at each station, means including a line circuit extending from said office to each of said stations for signaling between the office and any station when the corresponding control relay is actuated, means for actuating the control relay for the first station in said series from the office or from any station, and means effective upon the actuation of said first control relay for progressively actuating the control relays at other stations in said series.

39. Remote controlling apparatus comprising a dispatcher's office and a plurality of control relays located at spaced points, a line wire normally extending from said office to all of said points, means set into operation from any said point for at times sectionalizing said line wire at one of said points, means for supplying successive energy impulses to said line wire from said office, and means responsive to certain of said impulses for progressively extending said line wire to the remaining points to govern all said control relays in order.

40. A synchronous selector system comprising an office and a plurality of stations, and including a stepping wire and a common return wire connecting said office and each of said stations, and a station selecting wire from the first of said stations to said office, and from each of the remaining stations to the next preceding station, a synchronous selector at each of said stations, means controlled from said office over said station selecting wire and said common wire for selecting the station selector at the first station, means for selecting each remaining station selector, controlled from the next preceding station over said station selecting wire and said common wire, a circuit for operating each selected station selector including said stepping wire and common wire, and a synchronous selector at said office operated in synchronism successively with each of said station synchronous selectors.

41. In a remote control system comprising an office and a series of stations connected by a line wire, a selector at the office, a selector at each station, means for synchronously operating the selectors at the office and at each station comprising apparatus for disconnecting all but one of said stations from said line wire and for transmitting an impulse from the office to said one station, means responsive to the reception of an impulse at any station to cause the transmission

- of an impulse from said station to the office, means responsive to the reception of an impulse at the office to cause the transmission of an impulse to the station then connected to the line circuit, means responsive to a predetermined number of impulses alternately received and transmitted by any station to connect said line circuit to the next station of the series, and means effective upon completion of the operation of said office selector for resetting each of said selectors to a normal non-operating condition.
42. In a remote control system comprising an office and a series of stations connected by a line wire, a selector at the office, a selector at each station, means for synchronously operating the selectors at the office and at each station comprising apparatus for disconnecting all but one of said stations from said line wire and for transmitting an impulse from the office to said one station, means responsive to the reception of an impulse at any station to cause the transmission of an impulse from said station to the office, means responsive to the reception of an impulse at the office to cause the transmission of an impulse to the station then connected to the line circuit, means responsive to a predetermined number of impulses alternately received and transmitted by any station to connect said line circuit to the next station of the series.
43. A remote control system comprising an office and a plurality of remote stations connected by a first and a second line circuit, synchronous selectors at said office and at each of said stations adapted to be controlled over said second line circuit, means controlled over said first line circuit for operating each of said station selectors in turn in synchronism with said office selector, a plurality of devices at least one at each said station, means responsive to a change in position of any station device to set said synchronous selectors into operation, and means controlled by said synchronous selectors to indicate the condition of each of said station devices at said office.
44. A remote control system comprising an office and a plurality of remote stations connected by a first, a second, and a third line circuit, synchronous selectors at said office and at each of said stations adapted to be controlled over said second line circuit, means controlled over said first line circuit for operating each of said station selectors in turn in synchronism with said office selector, devices at said stations, and means controlled over said third line circuit and by said synchronous selectors for controlling said devices and for indicating their condition at said office.
45. A remote controlling system comprising an office and a plurality of stations, a series of counting relays at the office and a similar series at each station, means for transmitting a series of stepping impulses of which part originate at the office and part at a station, and means responsive to said impulses for operating the relays of said series in synchronism.
46. In a remote control system, an office and a plurality of stations connected by a normally open line circuit including a pair of line wires extending from the office through each station in turn, a line relay at the office in said circuit, sectionalizing means at each station effective when operated to open the portion of the line circuit leading from said station to the next station more remote from the office, starting means at each station for closing the portion of said line circuit leading from the office to said station to energize said line relay, and means responsive to the energization of said line relay for operating and restoring successively the sectionalizing means at each station in turn beginning at the station nearest the office.
47. In a remote control system, an office and a plurality of stations connected by line wires, a series of movable devices at least one located at each station, means set into operation by a change in position of any one of said devices for transmitting an impulse from the office to the nearest station, means at each station rendered effective when an impulse transmitted to such station is terminated for then initiating the transmission of an impulse from the office to the next station more remote from the office, means at each station controlled in accordance with the position of the movable device at such station for transmitting an impulse from such station to said office and determining the character of such impulse, indication means at the office for said movable devices, and means for controlling said indication means in accordance with the character of said impulses.
48. In a dispatching system for railroads, a control office, a plurality of stations located at different distances from the control office, a line relay in the control office, a line relay at each station, a common wire, a line wire divided into sections extending from the control office to the nearest station and from station to station, a neutral relay at each station having front contacts connecting the line wire section extending from the control office to that station to said line relay at that station, and back contacts connecting that line wire section to the line wire section extending to the next station more remote, and means including another line wire divided into sections for energizing and de-energizing said neutral relays at the several stations in turn to establish line circuits comprising said common wire and said line wire sections and extending from the control office to each station in turn only one station at a time, said line wire circuits each including the line relay in the control office and the line relay at the station then connected to the control office.
49. In a system of the character described, a control office, a plurality of stations located at different distances from the control office, a line relay at each station, a line wire section extending from the control office to the next station, other line wire sections extending from station to station, a transfer relay at each station having contacts connecting the line wire section extending toward the control office either to the line relay at that station or to the line wire section extending to the next more remote station, another relay at each station controlling the energization of the transfer relay, impulsing means in the control office for applying impulses to said line wire, and means including a starting circuit at each station for initiating operation of said impulsing means, said starting circuit including contacts of said another relay at that station.
50. In a system of the character described, a control office, a plurality of stations, two line wires divided into sections extending from the control office to the next station and from station to station, a line relay in the control office, a line relay at each station, means controlled over one of said line wires for connecting together the sections of the other line wire to establish line circuits each including the line relay in the

control office, and the line relay at each station in turn only one station at a time, and means in the control office for energizing said line circuits with time-spaced impulses of different polarity.

5 51. In a dispatching system for railroads, the combination with a control office and a plurality of stations, a line relay in the control office, a line relay at each station, a line wire divided into sections extending from the control office to the next station and from station to station, a transfer relay at each station having a front contact connecting the line wire section extending toward the control office to the line relay at that station, and a back contact connecting said line wire to the line wire section extending to the next station more remote, another line wire having sections extending from station to station, and another relay at each station at times energized over said another line wire for controlling the energization of the transfer relay at that station, whereby line circuits are established each including the line relay in the control office and the line relay at each station in turn only one at a time.

25 52. In a system of the character described, a control office, a plurality of stations located at different distances from the control office, a line relay at the control office, a line relay at each station, means including a line wire divided into sections for establishing line circuits extending from the control office to each station in turn only one station at a time, said line circuits each including the line relay in the control office and the line relay at the corresponding station, a device at each station having contacts operated in accordance with the condition of that device, and means comprising a partial circuit including certain contacts of said device and contacts of the line relay at the corresponding station for transmitting indications of the condition of said device to the control office.

40 53. In a communication system for train dispatching, the combination with a control office and a plurality of stations, line relays in the control office and at each station, a line wire divided into sections, impulsive means in the control office, means including said impulsive means for connecting together said line wire sections end to end to establish a plurality of line circuits each extending from the control office to one of said stations only, said line wire circuits each including the line relay in the control office and the line relay at the corresponding station, a track relay at each station, a storage relay at each station energized upon the deenergization of the track relay, means including a partial circuit through contacts of the line relay at the station for transmitting to the control office an indication of the condition of said storage relay, and means including a starting circuit at each station controlled by said storage relay for initiating operation of the impulsive means in the control office.

45 54. In a system of the character described for transmitting indications and controls between a control office and a plurality of stations located at different distances from the control office, a line relay at each station, a line wire divided into sections, a transfer relay at each station for connecting the line wire section extending to that station from the control office either to the line relay at that station or to the line wire section extending to the next station more remote, a device at each station having contacts operated in

accordance with its condition, means comprising a partial circuit including a contact of said line relay for transmitting to the control office current impulses of distinctive character according to the condition of said device, and means responsive to such impulses transmitting from each station in turn for operating the transfer relay at a particular station to extend the line circuit to the next station.

5 55. A system of the character described comprising, a control office, a plurality of stations, a line wire divided into sections, means including a relay at each station for establishing line circuits extending from the control office to each station in turn, each of said line circuits including a line relay in the corresponding station, a track circuit, circuit controlling means controlled by said track circuit, a communication circuit for each station including contacts of said line relay at that station and contacts of said circuit controlling means for transmitting current impulses to the control office from a field battery, and means responsive to said current impulses for operating said transfer means at the corresponding station to extend the sectionalized line circuit to the next station more remote.

10 56. A system for establishing a communication between a control office and a plurality of field stations one at a time in turn comprising, a line wire divided into sections, transfer means connecting said line wire sections together to form communication circuits extending to the several stations only one at a time, step-by-step means in the control office, means for energizing said communication circuits in turn with impulses of current from sources at said stations, and means in the control office responsive to such current impulses received from said stations for operating said step-by-step means.

15 57. A communication system for train dispatching comprising, in combination with a control office and a plurality of stations, a line wire divided into sections, step-by-step means in the control office, means including said step-by-step means for connecting together said line wire sections to establish communication line circuits between the control office and each of said stations in turn only one station at a time, a relay means in the control office causing operation of said step-by-step means to certain positions, and means for energizing said relay means from a source of current at each of said stations in turn to cause operation of the step-by-step means.

20 58. In a communication system of the character described, the combination with a control office and a plurality of stations, step-by-step means in the control office, relay means in the control office acting when alternately energized to operate the step-by-step means, a line relay at each station, a line wire divided into sections, means including one of said relay means in the control office energized in series with the line relay at each station in turn for causing operation of the step-by-step means in the control office, and means for energizing the other relay means in the control office in response to current from a source of current at each station in turn as the sectionalized line wire is extended to that station, whereby the step-by-step means in the control office is operated to successive stepping positions by current impulses alternately transmitted from the control office and the field stations in turn.

25 59. In a remote control system including a control office, a plurality of stations located different

75

- distances from said control office, a line wire divided into sections one section extending from the control office to the first station and other sections extending from station to station, a transfer device at each station for establishing a plurality of communicating circuits each extending from the control office to one station at a time only in turn, step-by-step means in said control office for causing successive operation of said transfer devices, two electro-magnets acting when alternately energized to operate said step-by-step means, one of said electro-magnets being energized on alternate steps in response to sources at the successive stations over said line wires, and the other electro-magnet being energized on other alternate steps from a source in said office.
60. In a communication system for train dispatching, a dispatcher's office, a plurality of way stations, a bank of neutral relays at each station, means for energizing the relays of each of said banks of neutral relays sequentially one at a time from the dispatcher's office, the last relay to be energized in each bank controlling the energization of all the other relays in that bank, means controlled from the office for allowing only one bank to have its relays sequentially energized at any one time, and means controlled from the dispatcher's office for controlling the energization of said last relay of each of said banks of neutral relays.
61. In a centralized traffic controlling system, a plurality of field stations, traffic controlling devices at each of said stations, a bank of neutral stepping relays at each of said stations for closing separate channel circuits for the control of said traffic controlling devices at that station, station selecting means for selectively rendering said banks of stepping relays available for operation at only one station at a time, automatic means for sequentially picking up the stepping relays of that particular bank rendered available for operation by said station selecting means, and means for maintaining picked up said stepping relays of any bank in operation until the end of the operation of such bank.
62. In a dispatching system for railroads, a control office, a plurality of stations located at different distances from the control office, a line relay at each station, a common wire, a line wire divided into sections extending from the control office to the nearest station and from station to station, electro-responsive means at each station having contacts for connecting the line wire section extending from the control office to that station to said line relay at that station when said electro-responsive means is in one condition and connecting the line wire section extending from the control office to the line wire section extending to the next station more remote when said electro-responsive means is in another condition, a series of stepping relays at each station, means for causing the electro-responsive devices at the stations to be successively operated without permitting operation of the series of stepping relays at the various stations, other means effective when a particular line relay is connected with the control office and providing that a message is to be transmitted to or from the station at which such line relay is located or causing the series of stepping relays at that station to be sequentially operated, and means for actuating the electro-responsive means at that station when the last stepping relay of said series at that station has been operated to connect the line

section extending to the next more remote station to said office.

63. In a selector system of the multiple impulse type for transmitting messages between a control office and any one of a plurality of stations, a plurality of field stations located different distances from said control office, a line relay at each station, a common wire extending to each of said stations, a line wire divided into sections extending from the control office to the nearest station and from station to station, a stick relay at each station for when energized connecting the line wire section extending from the control office to that station to the line wire section extending from that station to the next more remote station, a series of stepping relays at each of said stations, circuits for each of said series of stepping relays controlled by the associated line relay for causing sequential energization and picking up of said stepping relays only if said stick relay is deenergized, and means effective if no message is to be transmitted to or from a particular station for immediately upon selection of that station closing a pick-up circuit for the stick relay at that station and preventing successive energization of the stepping relays at that station.

64. In a selector system of the multiple impulse type for transmitting messages between a control office and any one of a plurality of stations, a plurality of field stations located different distances from said control office, a line relay at each station, a common wire extending to each of said stations, a line wire divided into sections extending from the control office to the nearest station and from station to station, a stick relay at each station for when energized connecting the line wire section extending from the control office to that station to the line wire section extending from that station to the next more remote station, a series of stepping relays at each of said stations, circuits for each of said series of stepping relays controlled by the associated line relay when rendered effective for causing sequential energization and picking up of said stepping relays only if said stick relay is deenergized, means effective if no message is to be transmitted to or from a particular station for immediately upon selection of that station closing a pick-up circuit for the stick relay at that station and preventing successive energization of the stepping relays at that station, and other means for causing said stick relay to be picked up when the stepping relays at that station have all been sequentially picked up.

65. In a communicating system of the multiple impulse selector type, a central office, a plurality of field stations located different distances from said office, a common line wire connecting the office with each field station, a line wire divided into sections extending from the office to the nearest field station and from station to station, a series of stepping relays in said office, a series of stepping relays at each station, a line relay at said control office included in said section of line wire extending to the nearest station, a line relay at each station, a stick relay at each station, means effective if said stick relay at a particular station is deenergized and all of the line wire sections between that particular station and the office are connected end-to-end and including the line relay at that particular station and the line relay in said office for causing the stepping relays at that station and at the control office to be sequentially energized and picked up

in synchronism by impulses in said line wire sections, and means for picking up the stick relay for that particular station when the last one of said stepping relays for that station picks up.

5 66. In a communicating system of the multiple impulse selector type, a central office, a plurality of field stations located different distances from said office, a common line wire connecting the office with each field station, a line wire divided 10 into sections extending from the office to the nearest field station and from station to station, a series of stepping relays in said office, a series of stepping relays at each station, a line relay at said control office included in said section of 15 line wire extending to the nearest station, a line relay at each station, a stick relay at each station, means effective if said stick relay at a particular station is deenergized and all of the line wire sections between that particular station and 20 the office are connected end-to-end and including the line relay at that particular station and the line relay in said office for causing the stepping relays at that station and at the control office to be sequentially energized and picked up 25 in synchronism by impulses in said line wire sections, means for picking up the stick relay for that particular station when the last one of said stepping relays for that station picks up, and means for picking up the stick relay for that particular station before sequential energization of 30 the stepping relays at that station when no messages are to be transmitted.

67. In a communicating system of the multiple impulse selector type, a central office, a plurality 35 of field stations located different distances from said office, a common line wire connecting the office with each field station, a line wire divided into sections extending from the office to the nearest field station and from station to station, 40 a series of stepping relays in said office, a series of stepping relays at each station, a line relay at said control office included in said section of line wire extending to the nearest station, a line relay at each station, a normally energized series of 45 stick relays one at each station normally connecting all said line wire sections end to end, means at said control office and at each of said stations for causing deenergization of all of said stick relays, means effective if said stick relay at a particular station is deenergized and all of the 50 line wire sections between that particular station and the office are connected end to end and including the line relays at said office and at said particular station for causing the stepping relays at that station and at the control office to be sequentially energized and picked up in synchronism by impulses in said line wire sections, and means for picking up the stick relay for that particular station when the last one of said stepping 55 relays picks up if a message is transmitted and for picking up such stick relay before sequential energization of the stepping relays at that particular station if no messages are to be transmitted.

68. In a communicating system of the multiple impulse selector type, a central office, a plurality 60 of field stations located different distances from said office, a common line wire connecting said office with each field station, a line wire divided into sections extending from the office to the nearest field station and from station to station, a line 65

relay at each station, a normally energized series of stick relays one at each station normally connecting all of said line wire sections end to end, means for causing deenergization of all of said stick relays, means for causing sequential energization of said stick relays starting with the stick relay nearest the office, means effective if said stick relay at a particular station is deenergized and all of the line wire sections between that particular station and the office are connected end to end for causing the line relay at that particular station to cause successive energization of the stepping relays at that particular station, and means for picking up the stick relay for that particular station when the last one of said stepping relays picks up if a message has been transmitted to or from that particular station and for picking up such stick relay before sequential energization of the stepping relays at that particular station if no message is to be transmitted to or from that particular station.

69. A synchronous selector remote control system comprising an office and a station, a stepping line and a message line connecting the office and said station, a line relay and a source of current 25 at the office and a line relay at said station in said stepping line, a series of contacts at the office, and a series of contacts at the station, each arranged to be closed one at a time in sequence as the corresponding line relay is actuated repeatedly, a plurality of intermittently available message circuits, each including said message line, a source of current, contacts of the station line relay and corresponding contacts of the series at the office end of the series at the station, 35 and means for transmitting current impulses over each of said message circuits when available.

70. A synchronous selector remote control system comprising an office and a plurality of stations, a stepping line and a message line connecting the office and each of said stations, a line relay and a source of current at the office and a line relay at each of said stations in said stepping line, synchronous selectors at the office and at each station; each including series of contacts 40 arranged to be closed in sequence as the corresponding line relay is actuated repeatedly, a plurality of intermittently available message circuits each including a source of current, said synchronous selector at the office, said message line and contacts of a line relay and synchronous selector 45 at a selected one of said stations, and means for transmitting current impulses over said message circuits when available.

71. A synchronous selector remote control system comprising an office and a station, a stepping line and a message line connecting the office and station, a line relay at the office, and a line relay at the station, each included in the stepping line, a chain of counting relays at the office arranged 50 to be energized one at a time in sequence as the office line relay is actuated repeatedly, a chain of counting relays at the station arranged to be energized in synchronism with the office chain by the station line relay, a series of message circuits, 55 one for each counting relay of the chain, each including said message line, contacts of corresponding relays of the office and station chains respectively, and contacts of the station line relay, and means for selectively controlling each 60 of said message circuits.

NEIL D. PRESTON.

DISCLAIMER

2,129,182.—*Neil D. Preston*, Rochester, N. Y. TRAIN DISPATCHING SYSTEM FOR RAILROADS. Patent dated September 6, 1938. Disclaimer filed March 1, 1939, by the assignee, *General Railway Signal Company*.

Hereby enters this disclaimer as to claims 13, 14, 15, 17, 18, 19, 23, 38, and 45 of said Letters Patent.

Also hereby enters the following disclaimer:

(1) Disclaims from claim 52 any system, such as disclosed in the Preston and Dicke Patent No. 2,082,463 for instance, in which more than one line wire divided into sections is required to establish "line circuits extending from the control office to each station in turn only one station at a time".

(2) Disclaims from claim 69 any system, such as disclosed in the Preston and Dicke Patent No. 2,082,463 for instance, in which "a series of contacts at the office, and a series of contacts at the field station" are closed in sequence as the corresponding line relay is actuated repeatedly by currents of alternate polarities.

(3) Disclaims from claim 70 any system, such as disclosed in the Preston and Dicke Patent No. 2,082,463 for instance, in which "a series of contacts" at the office and at the field station "arranged to be closed in sequence" are closed in sequence as the corresponding line relay is actuated repeatedly by currents of alternate polarities
